UNITED STATES PATENT OFFICE

WILLIAM S. GUBELMANN, OF BUFFALO, NEW YORK

CALCULATING MACHINE

Original application filed September 19, 1912, Serial No. 721,141. Divided and this application filed March 30, 1927. Serial No. 179,525.

This application is a division of my pending application S. N. 721,141 filed September 19, 1912, now Patent No. 1,817,451, of August 4, 1931, and is particularly directed to the keyboard features of the parent application, having to do primarily with the key locking, interlocking and releasing mechanisms but including as well other general and specific features of the key mechanism as a whole.

10 Among the many new and improved features of the keyboard mechanism which applicant has invented and embodied in this application may be mentioned the improved form of key locking and releasing mechanism whereby a key when depressed will be held in its operative position until a certain period in the operation of the machine and then automatically released, the means for this purpose being so arranged that as little burden as possible is placed upon the keys which are provided for controlling the functions and operations of a main operating mechanism. The construction of this mechanism is such that the keyboard may be converted 20 at will into either a "locked" or a "flexible" condition. If it is placed in the locked condition a key when depressed can only be released and restored to normal upon operation of the machine or by means of special correction keys. However, when the "flexible" condition of the keyboard is predetermined then depression of any other key in the same bank with a previously depressed key will serve to release such previously depressed key. An intermediate condition of the keyboard may also be obtained in accordance with the present invention and this may be termed a "semi-flexible" or "combination" condition, under which it is possible to depress a second key in a bank and thereby release the first but depression of the second key meets with additional resistance which serves as a warning that one key in the bank has already been depressed. Regardless of 30 the condition of the keyboard, whether flexible, semi-flexible or locked, the keys become positively locked in either "depressed" or un-depressed position upon commencement of an operation of the machine due to the provision of certain connections from the mech-

anism which releases the main operating parts of the machine.

Another feature of the present invention is the provision of a plurality of means for releasing any depressed amount keys. One 55 of these key releasing mechanisms is that which is automatically operated upon each normal operation of the machine, and it is so designed that the keys will be released early in the cycle of the operation of the machine, this being in the illustrative machine substantially at the end of the first half portion of the cycle. In addition to this automatic releasing mechanism there is provided a universal correction mechanism which is 60 manually operable to release all of the depressed keys simultaneously without necessitating an operation of the machine. In accordance with the present invention this mechanism operates in a large part through 65 the same train of mechanism that is employed for the automatic key release. Still another feature of the key releasing mechanism is the provision of individual release keys one of which is associated with the keys of each bank 70 and adapted to effect the release of the keys in each particular bank. This individual or column release mechanism is so constructed that it is no longer operable after an operation of the main operating parts of the 75 machine has once begun. Various other improvements which have been incorporated in the releasing mechanism will be apparent from the full description of this mechanism which will be given hereinafter. 85

Another phase of the invention has to do with the provision of means for permitting various keys to remain depressed during successive operations of the machine. This repeat mechanism is so constructed that the 90 automatic key releasing mechanism may be disabled either for the entire keyboard or for individual sections of the keyboard. The machine disclosed in the parent case is adapted to be operated by means of a spring 95 motor and a number of keys as well as a lever are provided for releasing this motor to permit it to operate the various portions of the machine. One of these motor release keys is connected by a suitable mechanism with the 100

automatic key releasing means so as to disable the latter and permit a set-up on the keyboard to remain for a subsequent operation. The individual bank repeating mechanism is so constructed that when one or more special keys are depressed the automatic key releasing train of mechanism is rendered ineffective so far as the particular bank or banks of keys selected are concerned, while the automatic release of keys in other banks remains undisturbed.

The machine herein disclosed is equipped with a bank of special shifting keys in addition to the regular amount key banks and while this special bank is provided with a number of the features which have been explained in connection with the amount key banks, there are other features which apply particularly to this shifting key bank. In view of the nature of the keys contained in this bank and the functions which they control within the machine, they are arranged in groups, the keys of one group having a different relation to the amount key banks from the keys of another group. This gives rise to a feature of the present invention which may be termed the "split bank" and it is through this special split bank construction that the keys of each group may have certain similar effects upon the various functions of the machine which differ from the effects of the keys of the other group. One such distinction which may be here pointed out is that of the provision of an interlock between the amount keys and the keys of one group of special keys while no such interlock is provided between the amount keys and the keys of another group of special keys.

Another feature which may be mentioned in connection with the special key bank as a whole is the provision of means for automatically releasing these keys upon an operation of the machine. The means for this purpose operates independently of the automatic releasing means for the amount keys and is operable at an entirely different stage in the cycle of operation of the machine. Whereas the amount keys are automatically released comparatively early in an operation of the machine the special keys are not released until relatively late in the operation.

Still another feature which is to be found in the special key bank but not in the amount key banks is the provision of means for preventing the depression of more than one key of a certain group of keys either simultaneously or in sequence. This is required in connection with certain keys in order to prevent an attempt to produce contradictory controls over the operation of portions of the computing mechanism. The form of single key mechanism which has been provided by this invention is such, furthermore, that either one of two keys or both may be depressed and caused to act upon a single element of this

blocking mechanism so as to prevent operation of any of the other keys associated with this mechanism.

The present invention further contemplates a special form of interlock between the two keys referred to above of this special key bank which keys are located in different ones of the two groups which have been mentioned. This interlock is of special construction and is so designed that the two keys may be depressed simultaneously or successively in a certain sequence but may not be depressed successively in the inverse order.

Another very simple but effective feature of the present invention is the provision of removable keyboard dividing bars which may be placed between any two banks of keys desired or may be completely removed from the machine. As many of these bars as may be required may be employed to divide the keyboard according to any system desired such as the American monetary system or the regular decimal system.

Among other novel and improved features of the keyboard which will appear from the detailed description are the construction of the keys themselves, the arrangement of springs for restoring the keys to normal, and the connections from the amount keys to certain differentially movable parts whose movements the keys are intended to control. The latter function is effected by means of a novel arrangement of the keys and cooperating stop bars. Still other improved constructions might be enumerated but reference may be had to the body of the specification as well as the claims for an explanation of such constructions.

In the parent application the keyboard, which has been discussed in the foregoing sections, is related to a calculating unit which, as has already been stated, is operated by a spring motor releasable by any one of a plurality of operating keys or by means of a hand lever. This calculating unit is disclosed in connection with a typewriting unit and the machine is so organized that both the calculating unit and the typewriting unit are capable of recording upon the same record material carried by suitable platen mechanism. It is another primary object of the present invention to combine these two units in such a way that they cannot be operated simultaneously and so that the results produced by either will not interfere with the results of an operation of the other. This necessitates the provision of interlocking connections between the typewriting keys and certain operative portions of the calculating unit and in the present machine this connection is adapted to be controlled by the keyboard of the calculating unit. One feature of this construction which may be mentioned is that conflict between the records produced by the typewriting mechanism and

the computing mechanism is avoided by maintaining the typewriter keys in locked condition after certain effective operations of the computing mechanism but, while idle, operations of the computing mechanism will not in any way interfere with subsequent operation of the typewriter mechanism.

Numerous other objects and advantages of the present invention will become apparent from the full disclosure which will be given hereinafter and it should be borne in mind that the foregoing serves to point out only a portion of the primary objects. It has been the general object of the invention to improve the construction of the keys and keyboard mechanism of calculating machines in all particulars and the specific objects above mentioned will serve to indicate the trend of the improvements which have been embodied in the present invention. An illustrative machine embodying the various features of the invention will now be described in detail with reference to the accompanying drawings which may be regarded as a part of the specification.

Of the drawings:

Fig. 1 is a plan view of the calculating machine showing particularly the arrangement of the keys on the keyboard.

Fig. 2 is a detail view in side elevation taken to the left of the special key bank.

Fig. 3 is a detail view of the keyboard mechanism in side elevation taken to the right of one of the banks of numeral keys.

Fig. 4 is a sectional elevational view showing a bank of amount keys and their relation to various operating portions of the machine.

Fig. 5 is a view similar to Fig. 4 but illustrating the position of the parts after the machine has been partially operated.

Fig. 6 is a detail of various connections operated by one of the special keys.

Fig. 7 is a sectional view in elevation taken to the left of the special key bank and illustrating various mechanisms operated by these keys.

Fig. 8 is a detail in plan view of certain single-key mechanisms provided for the special key bank.

Fig. 9 is a transverse sectional view in elevation omitting various parts and showing particularly the keyboard and some parts co-operating therewith.

Fig. 10 is a detail of certain connections operated by the operating keys and the operating handle.

Fig. 11 is a detail in elevation of the plurality of operating keys and certain of their connections.

Fig. 12 is a plan view in section taken on the line 12-12 of Fig. 4 and showing the mechanism associated with the keyboard and located directly below the keyboard plate.

Fig. 13 is a fragmentary vertical section taken in front of the foremost line of keys.

Fig. 14 is a vertical longitudinal section of the keyboard showing one of the keys depressed and the parts in the position which they occupy preparatory to operating the machine.

Fig. 15 is a similar view showing the position of the parts while the machine is being operated.

Fig. 16 is a fragmentary view similar to Figs. 14 and 15 but showing the parts set for converting the keyboard into a lock keyboard.

Figs. 17, 18 and 19 are detached side views of the stop bar, locking bar and releasing bar, respectively, for each row of keys and parts connecting therewith.

Fig. 20 is a view similar to Figs. 14 and 15 showing the special shift keys and connecting parts.

Fig. 21 is a fragmentary vertical cross section of the keyboard showing the means for holding the keys yieldingly in their elevated position.

Fig. 22 is a fragmentary vertical longitudinal section of the column lock or repeating mechanism.

Fig. 23 is a perspective view of the key tensioning device.

Fig. 24 is a fragmentary sectional view showing the means for rendering the keyboard either flexible or lockable.

Fig. 25 is a detail perspective view of a keyboard dividing element.

Fig. 26 is a perspective view of the key releasing mechanism operated by the universal error key.

Fig. 27 is a vertical section through the entire machine showing the relation between the computing machine unit and the typewriter.

Fig. 28 is a fragmentary perspective view of certain key detents and associated bails.

Fig. 29 is a top plan view of the typewriter keyboard.

Fig. 30 is a fragmentary top plan view of the typewriter key levers and adjacent parts.

Fig. 31 is a perspective view of a part of the mechanism connecting the typewriter and adding machine unit.

Fig. 32 is a perspective view of an interlock between two special keys.

Fig. 33 is a fragmentary horizontal section showing means for locking a shift key in depressed position.

Fig. 34 is a perspective view of certain parts of the interlock between the typewriter mechanism and the adding machine unit.

Fig. 35 is a fragmentary elevational view showing connections from a special shift key.

General organization of the machine

As has already been mentioned the machine disclosed in the parent case is a combined computing machine and typewriter in which the computing machine unit is adapt-

ed to perform various types of calculation and is adapted to record the quantities entering into the calculation. The machine as a whole is so designed that the computing unit 5 may be completely removed from the typewriter and operated independently of the latter. When inserted in the typewriter frame, however, certain connections are provided between the two units so as to prevent confusion in the operation of the two 10 and so as to permit recording upon a common record sheet.

Considering first the computing unit, said unit is provided with suitable supporting 15 frames comprising a base plate, a pair of side frames and a pair of vertical intermediate frames. All of these frames are suitably supported upon the base plate and are held in position by any suitable means so as to provide 20 supports for the various operating shafts and other parts of the computing machine mechanism. The keyboard of the computing unit which is one of the primary features to be covered by the present application 25 is adapted to control the various functions performed by the other mechanisms in the machine. The construction is such that depression of the keys will shift certain elements within the machine to control the operation 30 of other elements upon the operation of a main operating shaft. The various sections of the machine having a direct bearing upon the construction and operation of the keyboard will now be described in detail, 35 reference being made first to the general operating parts.

Main operating frame mechanism

For the purpose of operating the various 40 portions of the calculating machine under the control of the mechanisms set directly by the keys on the keyboard, there is provided a chain of operating mechanism only a portion of which need be described in this application. Referring particularly to Figs. 4 and 45 5, a shaft 108 is provided and may be termed the main operating shaft of the machine. A crank pin 111 is carried by a pair of discs secured to shaft 108 and it will be apparent 50 that in the rotation of the shaft the crank pin will have a certain extent of vertical reciprocation. A link 120 connected at its lower end to the crank pin 111 and at its upper end to a rearwardly extending arm 119 of a three-armed frame pivoted about a supporting shaft 55 26 serves to transmit movement from the main shaft to various portions of the machine. A forwardly extending arm 116 of the three-armed frame is connected by means of a link 60 118 to cross-rod 112 which is carried by a pair of arms such as 114, shown in Figs. 4 and 5, loosely mounted upon a supporting shaft 36. A corresponding link similar to 118 is provided at the opposite end of the cross-bar 112 65 and is connected to an arm very similar to

116 on another rockable frame. The third arm 123 of the three-armed member together with a corresponding arm of the other rockable frame carries at its lower end a cross-rod 121 which, as more fully disclosed in the parent application, serves to control the operation of a series of actuating devices for the totalizer wheels and printing elements which do not form a part of the invention to be covered by the present divisional case. 75

The number setting key mechanism

Passing now to the construction of the number key banks of the calculating machine keyboard the functional relation of the parts, such as pointed out in the statement of objects of the invention, will first be briefly reviewed and then the details of the mechanism will be explained. 80

The number key setting mechanism is constructed to provide the following: 85

First, means whereby the setting keys are locked down after being depressed until released by the operation of the machine.

Second, means whereby all the setting keys are locked against movement during the operation of the machine.

Third, means whereby the setting keys that have been depressed are released and restored and the setting keys that have not been depressed but have been locked against movement during the first part of the operation of the machine are released so that they can be set for a subsequent operation before the return movement of the actuating gears and operating mechanism and before the end of the forward movement of the operating lever, thus enabling the setting keys to be set for a subsequent operation before the completion of the preceding operation. Such a setting of keys may be made immediately after the hand leaves the operating lever at the end of its forward stroke. 100

Fourth, means are also provided whereby the machine may be made to cause a wrongly depressed key to be released by the depression of the correct key in the same column, in other words a "flexible" keyboard. 110

Fifth, the "flexible" keyboard may be altered by the machine operator into a "locked" 115 keyboard, in which any number key, upon being depressed, is locked in depressed position and all the remaining number keys in the same column are locked against depression. With this setting a wrongly depressed key can be released before the operation of the machine only by the use of an individual column release or correction key located at the top of the row of keys, or by a universal correction key. 120

Sixth, the keyboard may also be conditioned by the machine operator when desired to produce a combination keyboard combining the advantages of both flexible and locked 130 keyboards, allowing the easy depression of

one key in a column but offering substantial resistance to the depression of a second key in the same column without positively locking the column. With this setting depression 5 of a second key releases the first key but requires considerable more force than is required to depress the first key. This additional resistance serves to notify the operator that a key has already been depressed in that 10 column and thereby guards against error.

The key setting mechanism is constructed as follows:—

210, Figs. 1, 3, 4, 5, 14, 15, 16 and 21, represents the number setting keys, which are arranged in parallel longitudinal rows or columns, there being nine of such keys in each row and as many rows as are required to provide the intended capacity of the machine. Each of these keys is provided with a 15 pending stem or shank 211 which is guided in upper and lower guide plates 212 and 213 at the top of the machine so as to be capable of vertical reciprocation therein. The key shanks are flat sided and their guide openings are of corresponding form to prevent their turning. The setting keys are normally held in an elevated position by a plurality of coil springs 214. A row of these springs is arranged under the lower guide 20 plates 213 between every two rows of keys and each spring has its ends connected with the lower ends of a pair of keys in adjacent rows. The coils of the springs 214 in each 25 row are mounted on a longitudinal rod 215 which is supported at opposite ends on the under side of the lower guide plate 213, as shown in Figs. 4, 5, and 21. Each setting key is provided in its shank or stem between the upper and lower guide plates with upper 30 and lower openings 216 and 217. Extending lengthwise through the lower openings of the several key shanks in each row is a set of three longitudinally movable bars 218, 219 and 220 which are arranged side by side. 35 The stop bar 218, Fig. 17, at the left of each of these sets is connected at its front end with the upper arm 221 of one of a series of differential stop levers 35, Figs. 4, 5, 12 and 13, and is provided on its upper side with a 40 series of stop lugs 222. Each stop lug has an abrupt front side and an inclined rear side and is adapted to co-operate with the upper edge of the lower slots 217 in one of the setting key stems. Each stop 222 is 45 spaced a distance from its respective key stem so that when its stop bar 218 is arrested in its forward movement by any one of said stops 222 engaging a depressed key, the companion differential stop lever 35 will be arrested in a position to present one of a series 50 of stops 37 thereon in the path of the front end of an actuating gear segment 25, and arrest said gear segment after a forward movement corresponding to the value of the 55 key depressed. Thus the number "one" key

has its stop so located that when its stop bar is arrested by its stop 222 engaging its key stem the corresponding stop lever 35 will have its number one stop 37 in the path of gear segment 25, and limit the forward movement of said gear to one step or tooth. Number two key has its stop so arranged that it will in a like manner limit the forward movement of the actuating gear to two teeth or spaces and so on through the series. 70 In rear of its stop lugs each stop bar 218 is provided with a single main detent tooth 223 and in rear of said main detent tooth with a series of closely spaced auxiliary detent teeth 224 arranged lower than the main detent tooth and corresponding in number to the stop lugs 222, and each having an abrupt front side and an inclined rear side, as will be seen in Fig. 17. The upper arms 221 of the differential stop levers are spaced far apart while the lower arms 35 thereof and the mechanism cooperating therewith are spaced close together. For convenience in manufacture these upper and lower arms of the differential stop levers are made straight and journaled on the transverse rod 36 and each pair of corresponding arms 221 and 35 is connected by a yoke 225, the several yokes varying in length according to the distance between the respective arms and arranged to avoid interference with each other, as shown in Figs. 4, 5, and 13.

The locking or central bar 219, Fig. 18, of each set is provided on its upper side with a plurality of rearwardly projecting hooks 226 one of which is adapted to engage with the upper opening 216 of each setting key. Each of these hooks has its bill provided at its rear end with a rearwardly inclined upper face 227 forming a cam, and with a forwardly inclined lower face 228. At its rear end each locking bar is provided with a rear stop 229 and in front of said rear stop with low, middle and high stop shoulders 230, 231 and 232 arranged respectively one in advance of the other. Between its hooks and stop shoulders the locking bar is provided with a correction lug 233 having an inclined rear face 234 and an upper face 235 parallel with the edges of said rod 219.

At its extreme rear, projecting to the right the lock bar is provided with a lug 236 to which is attached the spring 237 which tends to normally draw the lock bar rearwardly. At its front end the locking bar 219 is provided with a laterally projecting pin or shoulder 238, Figs. 12 and 13, and between said shoulder and the hooks 226 with an upwardly projecting restoring lug 239, as shown in Figs. 14, 15, and 18. 240 represents a plurality of vertically swinging tension fingers or arms which are pivoted loosely on a transverse rod or shaft 241 in the upper front part of the machine and each having a flat upper front face 242 and an abrupt face

or shoulder 243 in rear of the plain face, as shown in Figs. 3, 4, 5, 12, 13, 14 and 15. Each of the tension fingers is yieldingly pressed against the under side of the shoulder or pin 238 of its respective locking bar 219 by a spring 282a (Figs. 12 and 13) and is provided adjacent to the restoring lug 239 of the locking bar with a similar lug 244, as best shown in Figs. 3 and 14. Transversely in rear of the lugs 244 and 239 of the several tension fingers 240 and locking bars 219 a universal restoring bar 245 is arranged and secured at opposite ends by means of arms 246 and 247 to the rock shaft 241, as shown in Figs. 3, 4, 5, 10, 12, 13, 14, 15 and 22. This shaft is turned in the direction for engaging the lugs 244 and 239 and shifting the same forward by means of a vertically swinging rock arm 248 pivoted on the horizontal shaft 26 having a shoulder or lug 249 adapted to be engaged by the right arm 123 of the operating frame during the last portion of the forward movement of the same, and a link 250 connected at one end with the free end of said rock arm 248 and at its opposite end with a rock arm 251 on the rock shaft 241, as shown in Figs. 4, 5, 10 and 13. The backward movement of the universal bar 245 is effected by a spring 252 which is preferably connected with the rock arm, as shown in Figs. 4 and 5.

Releasing bar

The right or releasing bar 220 of each set is provided on its upper side with a plurality of lugs 253, which have inclined rear sides 254 and each of which is adapted to co-operate with one of the setting key stems. At its rear end the releasing bar is provided with an upwardly projecting lug 255 having an inclined face or cam on its front side and a downwardly projecting lock finger or hook 256, as shown in Fig. 19. When free each releasing bar is moved rearwardly by a spring 257 shown in Fig. 12. The locking and releasing bars 219 and 220 are only capable of longitudinal movement but the stop bar 218 is capable of both longitudinal and vertical movement for a purpose to be hereinafter described. Normally each stop bar 218 is yieldingly held in its elevated position by a rock shaft 258 journaled on top of the lower guide plate 213 and having arms 259 at opposite ends which project laterally below notches 260 in the under side of the locking and releasing bars 219 and 220 of a set, into engagement with the under side of the respective stop bar, and a spring 260a applied to the rock shaft 258 and operating to turn the same so as to lift the stop bar 218, as best shown in Fig. 12, and partially shown in Figs. 3, 4, 5, 14 and 15.

261 represents a plurality of releasing pawls or dogs each arranged transversely above the rear end of one set of stop, locking

and releasing bars, and supported at opposite ends by two rock arms 262 which are mounted loosely at their rear ends on a transverse rod or shaft 263 arranged in the rear upper part of the machine. In the normal position of the parts, each of the releasing pawls 261 engages with its front side against the middle shoulder 231 of the locking bar 219 and holds the latter against backward movement, while its rear side is engaged by the detent lug or shoulder 223 of the stop bar 218 and the rear cam 255 of the releasing bar 220, as shown in Figs. 4, 17, 18 and 19. 70 75 80 85 90 95 100 105 110 274 being limited by a stop 277 on the frame. 5 278, Figs. 4, 5, 12, and 14, represents a horizontal universal stop bar arranged transversely above the several detent pawls 264 in rear of the stops 229 on lock bars 219, and supported at opposite ends by rock arms 279 which are mounted loosely at their rear ends on the transverse rod or shaft 263 and the universal stop bar 278 rests with its weight 10 on the detent pawls 264.

280 represents column correction keys one arranged at the upper end of each row or column of keys, as shown in Figs. 1, 4, 5, 14, 15 and 16, and which are of similar construction to the number keys 210 with the exception that the upper opening 216 in the shank 211 may be omitted but for convenience in manufacturing it may be retained. In its normal or raised position the upper part of 20 the lower slot 217 of said keys 280 is in rear of the cam face 234 of the correction lug 233 on the lock bar 219.

The operation of the setting mechanism thus far described is as follows:—

25 In Figs. 4, 17, 18 and 19 the several parts of the mechanism are shown in their normal position in which all of the keys are elevated, the stop bars 218 and the releasing bars 220 are in their rearmost positions. The inclined rear side 254 of the lugs 253 on the releasing bars 220 abut against the upper side of the lower opening 217 in the number key stems 211, as shown in Fig. 4, and the locking bars 219 are in their foremost position, 30 the several releasing pawls 261 are depressed and engage with the abrupt front side 223 of the detent lugs of the stop bars 218 and the middle stop shoulders 231 of the locking bars 219, and the several detent pawls 264 engaged 35 with the foremost auxiliary detent tooth 224 of the several series on the several stop bars 218 and the respective tension fingers 240 rest with their plain front faces 242 against the latterly projecting pin or shoulder 238 of their respective lock bar 219 offering 40 practically no resistance to the movement of the lock bars, as shown in Fig. 4.

Assuming now that key number 5 of a series 50 is depressed, as shown in Fig. 19, the upper edge of the lower opening 217 of its stem will first engage the inclined rear side 254 of the adjacent lug 253 of its respective releasing bar 220 and shift the latter forwardly into the position shown in Fig. 14, causing its rear lug 255 to raise its respective releasing pawl 261 sufficient to disengage it from the stop 55 223 on the respective stop bar 218 which is, however, still held against forward movement by the detent pawl 264; and to disengage 60 the said releasing pawl 261 from the middle stop 231 of its respective lock bar 219, allowing it to move rearwardly until arrested by its rear stop 229 against the universal stop bar 278. This movement of the lock bar 219 65 is just sufficient to allow its hook 226 to pass

through the upper opening 216 of said key stem 211 and lock the latter in its depressed position, bringing the cam face 227 of the hook in line with the upper edge of the lower slot 217 of the keys of the row not in the depressed position, and to move the laterally projecting pin or shoulder 238 on the displaced lock bar 219 rearwardly, allowing its tension finger 240 to rise under the tension of its spring 282 and present its abrupt face or shoulder 243 against the pin 238 on its respective lock bar. 70

The effect of the above is that when a number key is depressed in any column its respective stop bar 218 is released from its releasing pawl 261 but is still held against movement by its detent pawl 264 in engagement with its tooth 224, and the number key depressed is held in the depressed position, but should it be desired to depress another key in 80 the same column instead of the one already depressed, as for instance the first key depressed is an error, the second key may be depressed and by so doing the upper face of the lower opening 217 of its stem engages the inclined cam face 227 of the hook on its lock bar and forces the latter forwardly, thereby withdrawing its hook 226 from the opening 216 of the previously depressed key. The continued downward movement of the second 85 key brings its upper opening 216 in line with its hook 226 on the lock bar 219, allowing it to enter and lock down said key. As the lock bar is forced forward by the last depressed key, its pin 238 engages the abrupt 90 face 243 of its respective tension finger 240, which offers considerable resistance to the forward movement of the lock bar and the depression of any key in the same column subsequent to the first key depressed in said 95 column, the purpose of which is to notify the operator that a key has previously been depressed in this column should he by mistake have depressed a second key in the same column. This is what I term the "combination keyboard" as it combines the advantages of both the lock and the flexible keyboard, 100 but this keyboard can be changed into a lock keyboard or a flexible keyboard as will be described. 105

Column correction key

If it is desired to release a key that has been depressed or set in a column, it may be accomplished by depressing the column correction key 280 situated at the head of the row or column of keys. When the latter is depressed the incline 234 of the correction lug 233 on the related lock bar 219 is engaged by the upper end of the opening 217 of the correction key stems 211, and causes the lock bar to move forwardly and disengage its hook from the lower side of the upper opening of any depressed key thereby releasing it, the correction key again rising by the 110 115 120 125 130

action of its spring 214 immediately as the pressure on the same is released.

- After the desired keys have been set and the machine is operated, by depressing its operating lever or one of its operating keys, and during the first part of the forward or downward movement of the operating lever or keys, which latter will hereinafter be more fully described, the rock arm 269 and with it the trip dog 268, Figs. 3 and 10, are raised by the operating mechanism, the trip dog raising the universal releasing bar 266 which in turn raises all the detent pawls 264, releasing all the stop bars 218 and allowing such of them and their respective stop levers 35 as have been also released from their respective release pawl 261 by the setting of a key to move forward by the action of the spring 281 until arrested by the stop 222 corresponding to the key depressed. In this movement the stop 37 on the stop lever 35 corresponding to each operated key depressed is moved into position to arrest the gear segment 25 after it has moved a number of spaces or teeth corresponding to the value of the depressed key. The operating mechanism is constructed to, at the beginning of its movement, release the stop bars 218 and the latter and the stop levers 35 are moved by the springs 281 in advance of the gear segments until arrested by the bar 112, after which the operating frame, of which the bars 121 and 112 are a part, is moved allowing the gear segments to move and the stop levers to continue their movement in advance of the gear segments until arrested by the key depressed after which they arrest the forward movement of their respective actuating gear segments in a position corresponding to the key depressed.
- The raising of the detent pawls 264 at the initial part of the operation of the machine also raises the universal stop bar 278, which lies on the detent pawls, thus moving it out of the path of the rear stop 229 on the lock bars 219 and allowing them to move rearwardly by the action of their springs 237 until arrested by their high stop 232 engaging the front side of the release pawls 261; this allows the hooks 226 to move rearwardly in the lower slot 217 of all the number keys that have not been depressed in said row, moving the incline face of the hooks 226 beyond the path of the upper side of the lower opening 217 in the key stems and in its stead presenting the flat upper side of the hook and securely locking all the keys against movement, thereby preventing the depression of any of the number keys in a row where one key has already been depressed after the machine has started to operate, as shown in Fig. 15. In a similar manner the correction lug 233 is moved forwardly until its upper flat face 235 is moved under the upper side of the lower slot 217 of the correction key

280 and thereby preventing the correction key from being operated after the machine has started to operate, as also shown in Fig. 15.

The raising of the trip dog 268 simultaneously raises the longitudinal trip bar 270 until its pin 275 is moved above the shoulder of the retaining dog 274, and the latter is drawn to engage its shoulder under the said pin by the action of the spring 276 and thereby retains the trip dog 268, the longitudinal trip bar 270 and the universal releasing bar 266 together with the several detent pawls 264 in their elevated position, allowing the stop bars to move free of said detent pawls. As the operation is continued and the operating frame nears the end of its forward movement and after it has moved sufficient to allow a gear rack arm 25 to reach the nine position, its arm 123 engages the finger 249 on the vertically swinging rock arm 248 and raises it, and through the medium of link 250 and arm 251 moves the universal restoring bar 245 forwardly, engaging the restoring lugs 239 of the lock bars 219, moving said lock bars forwardly until the middle stops 231 are in a position in advance of the releasing pawls 261 and withdrawing the hooks 226 of the lock bar 219 out of engagement with and releasing the keys depressed. The keys are restored to their normal or raised position by their springs 214. At the same time the universal restoring bar 245 engages the lug 244 on the tension fingers 240, moving its abrupt face or shoulder 243 out of the path of the pin 238 of the stop bar and preventing the tension fingers from resisting the forward movement of the lock bars.

Simultaneously with the forward movement of the restoring bar 245 and actuated by the same mechanism the trip bar 270 is moved rearwardly, and as the retaining dog 274 is prevented from moving rearwardly by the pin 277 the pin or shoulder 275 moves out of engagement with the dog 274, allowing the trip bar 270, trip dog 268, the universal bar 266 and the detent pawls 264 to drop to the lower position, and the detent pawls to engage the teeth 224 of the stop bars 218, preventing the forward movement of the stop bars by the spring 281. The construction is such that the detent pawls engage said teeth before the stop bars are released by the depressed key. When the number key is thus released its release bar 220 is freed to move rearward by its spring, to the position shown in Fig. 4.

On the early part of the return movement of the operating frame the arm 123 moves rearwardly, allowing the rock arm 248 and the link 250 to move downwardly and the universal restoring bar 245 to move rearwardly, which allows the lock bar to be drawn rearwardly by its spring sufficient for its middle stop 231 to be engaged by the re-

lease pawls 261 and thus arrest the further rearward movement of the lock bars 219, and also allows the tension fingers 240 to engage the pin 238 on its respective lock bar 219 with its plain front face 242, offering practically no resistance to the depression of a number key. As the operating frame continues on its return movement its stop bar return rod 112 moves forwardly and forces the stop levers 35 forwardly and the stop bars 218 rearwardly to their normal position, in which position the stop bars are again engaged and retained by the detent pawls 264 and by the release pawls 261, as shown in Fig. 17. During this movement of return rod 112 the gear racks and arm 25 are forced rearwardly out of the way of the stop levers 35 by the universal segment return bar 121 and the presser fingers 125. The detent pawls 264 when in engagement with the teeth 224 on said stop bar allow the latter to move freely rearwardly but prevent their forward movement by the spring 281.

When the keyboard is used in the foregoing manner it is what I term a "combination" keyboard, because it combines as before described the advantages of both the "flexible" keyboard wherein a wrongly depressed key may be corrected by simply depressing the correct key in the same column and the "lock" keyboard which prevents the depression of a second key in the same column.

Flexible keyboard

25 If for any reason it may be desired to make inoperative the means which increase the resistance to the depression of a second or correct key, following the depression of a wrong key or in other words make the keyboard what is commonly known as "flexible", this may be done by the following means:

282 represents a universal shifting or throw-off bar which is arranged transversely over the front ends of the several resistance 45 or tension arms 240 and mounted at opposite ends by means of rearwardly projecting rock arms 283 on the shaft 241, as shown in Figs. 4, 5, 14, 15 and 23. This bar is normally held in an inoperative position by means of a spring 284.

285 represents a shifting key arranged in an opening 286 in the top plate of the keyboard and pivoted at its lower end on one of the supporting arms 283 of the throw-off bar 282. On one side the shifting key is provided with an upwardly facing shoulder 287.

Upon depressing this key the throw-off bar moves all of the resistance arms 240 downwardly out of operative relation with the lock bars 219 and prevents any resistance to the depression of the number keys by the tension fingers 240 and making the machine what is known as a flexible keyboard without the advantages of the lock keyboard, and upon moving the shift key laterally while

thus depressed so that its shoulder engages the under side of the top plate then the throw-off bar will be held in its operative position. Upon disengaging the shifting key 285 from the top plate, the throw-off bar 70 is permitted to be raised by the spring into its inoperative position whereby the tension fingers are allowed to become operative.

The key 285 has a laterally projecting finger 288 to which one end of the spring is 75 attached while the other end of said spring is attached to the lower plate of the keyboard, this construction serving to provide the tension both for raising the bar 282 and forcing the key 285 forward as shown in Fig. 23. 80

Lock keyboard

When it is desired to obtain what is known as a lock keyboard in which the first key depressed in each row is locked down and incapable of correction except by means of a correction key and whereby every other key in the row is locked against depression when a key has been depressed in that row this may be done by raising the universal stop bar 278 90 so that it will not be engaged by the rear ends or shoulders 229 of the locking bars. When bar 278 is thus raised the locking bars when released are moved rearwardly by their springs 237 until arrested by their stops 230 95 against their detent pawls 264, whereby their hooks 226 enter the openings in their respective number keys to such an extent as to present the upper flat sides of said hooks to said keys, as shown in Fig. 16, whereby the number keys of the column are all locked against depression and the key that has been depressed is locked down. 100

In this position the inclined rear face 234 of the correction lug 233 on the lock bar is 105 still under the upper face of the opening in the correction key 280, as shown in Fig. 16, and a wrongly depressed key can be released by depressing said correction key, whereby said lock bar will be moved forwardly sufficiently to withdraw its hooks to release the key depressed and return said bar to its normal position, as shown in Figs. 4 and 18. 110

The raising of the universal stop bar 278 is effected by a shifting key 289 connected with one of the supporting arms 279 of said bar and projecting upwardly through an opening 290 in the top plate of the keyboard. When raised the shifting key 289 may be held in this position together with the universal stop bar connected therewith by a downwardly facing shoulder 291 formed on the shifting key 289 and adapted to engage with one edge of the opening 290, as shown in Figs. 2, 3 and 24. 115

Operation of machine locks all the number keys

The locking of all the number keys in the columns where no key has been depressed 130

when the machine is operated is accomplished as follows:—

- The rear locking hook 256 on the release bar 220 in said columns is normally in a position above and to the rear of the universal releasing bar 266, as shown in Figs. 4 and 19. During the first part of the operation of the machine, the universal bar 266 is raised and is thereby moved in front of the hook 256 of 10 each of said release bars 220, locking them against forward movement and thereby preventing the depression of any number key in any of the associated columns; the subsequent release of bars 220 is accomplished at 15 the same time that the keys in the rows where a key has been depressed are released, i. e., when the universal detent pawl releasing bar 266 is permitted to move down out of the path of said hook 256.
- 20 The rear locking hooks 256 on the release bars of the rows in which a key has been depressed are positioned forward of the universal detent pawl releasing bar 266, as shown in Fig. 15.

25

Early setting keys

Whether the machine is set for lock, flexible or combination keyboard functioning, it is possible to set said keys for a subsequent 30 operation while the last operation is still in progress, or immediately after the operating lever has reached the end of its forward movement and during the time that it is returning to its rearward or normal position, 35 whereby much time may be saved which is usually lost by an expert or rapid operator in being compelled to wait, after his hand has left the operating lever at the end of the forward stroke of the same, until the operating 40 lever has returned to its normal position.

If, during the operation of the machine and shortly after the set number keys have been restored, the operator depresses other keys in the same columns, the operation will 45 be as follows:—

As has been described, the detent pawls 264 are lowered to engage the teeth 224 on the stop bars 218 immediately before the depressed keys are released and allowed to 50 be raised by their springs, the purpose of which is to prevent the stop bars 218 and stop levers 35 from being moved forward by the spring 281 when released from said keys and thereby prevent the proper control of the 55 accumulators during the remainder of the operation. When the bar 112 of the operating frame in its return movement reaches the stop lever 35 it moves the latter forwardly and its stop bar 218 rearwardly and when 60 during this rearward movement of said stop bar one of its stops 222 approaches a key depressed, it would be prevented from further rearward movement by said key and in order to avoid this interference by said key 65 the stop bar is permitted to move bodily

downwardly to permit its stop to pass said key as follows:

As the stop bar 218 moves rearwardly the rear inclined face of its stop in engaging the depressed key forces the stop bar downwardly and as the stop bar 218 is yieldingly supported near its opposite ends by the arms 259 of the rock shaft 258 it is enabled to move downwardly to allow its stop or stops to pass said key, and in this manner the stop bar is moved rearwardly to its normal position ready to be again moved forward at the next operation of the machine under the control of its key already set.

As shown in Figs. 4 and 5 a pin and slot 80 connection between each stop bar 218 and its lever 221 permits the downward movement of the stop bar with respect to the lever.

Column lock or repeat

85

Means are provided whereby any of the keys of one or more columns when depressed may be made to remain depressed during any 90 number of operations while the keys of the other columns are automatically released at the end of each operation. As many columns of keys as desired may be equipped with this device, illustrated in Figs. 2, 7, 18, 20 and 22, 95 which is preferably constructed as follows: The restoring lug 239 is formed on the end of an arm 382, Figs. 20 and 22; this arm is pivoted at 238 on the front end of the lock bar 219. A key lever 383, pivoted at its lower end on said arm 382 between its lug 239 and its pivot, passes through an elongated opening in the upper guide plate of the keyboard, is provided at its upper end with a finger piece, and at its lower end with a rearwardly extending finger to which is attached a spring 384 the other end of which is attached to the upper guide plate 212. A pin 385 passing through and secured to said key lever 383 limits its upward movement through said guide plate by said spring. In its normal position, as shown in Figs. 18 and 20, the key lever 383 swings on its pin 385 as a fulcrum as the lock bars 219 are moved back and forth, and the restoring lug 239 is in its normal or elevated position ready to be engaged by the universal restoring bar 245 to withdraw the hooks 226 of the lock bars 219 from the keys and release them, as has been described. When it is desired to prevent this restoration of the keys in any column equipped with this column repeating device 110 the key 383 is depressed and allowed to move forward to engage its hook 386 under the plate 212, thereby depressing the lug 239 below the path of the restoring bar 245 thereby 115 and preventing the restoration of the keys of that column at the end of each operation so long as the key 383 is allowed to remain in the locked position, as shown in Fig. 22.

The identifying shifting keys and late restoring device

361, 337, 346, 362, 363, 364, 365, 366, 367 and 5 368, Figs. 1, 2, 7, 12 and 20, represent a number of identifying shifting keys constructed similar to the number keys and arranged in a longitudinal row, parallel with and to the left of the number keys. This arrangement 10 of the identifying shifting keys facilitates their manipulation with the left hand while the right hand is engaged in setting the number keys and manipulating the operating key or lever, and also facilitates the manufacture 15 of the machine, these keys being in close proximity to the mechanism to which they are connected.

The particular functions which the various identifying shift keys are adapted to control 20 during an operation of the machine form no part of the invention which it is intended to cover in this divisional application. It may be briefly mentioned, however, that these keys are designed through suitable connections to 25 exert definite controls over the accumulating mechanism as well as the printing mechanism of the calculating machine unit more fully disclosed in the parent application.

This row of keys has its differential stop 30 bar 369 arranged to the right and its releasing bar 370 and 371 to the left of the central locking bar 372 and is preferably so constructed that the latter does not release to restore the depressed key until the operation of the 35 machine is completed or nearly completed.

An individual U shaped restoring frame or lever 373, Figs. 2, 6, 7, 12, 13, 20 and 26, is pivoted on the shaft 241 in position to engage 40 when desired the toe 239 of the locking bar 372. This restoring frame or lever is operatively connected with the main operating frame 122 so that the lever will be moved to restore or release the identifying shift keys 337, 346, 362, 363, 364, 365, 366, 367 and 368 45 when the operating frame 122 approaches the limit of its return or downward movement.

The preferred means of accomplishing this is as follows:

The restoring frame or lever 373 is provided 50 with a forwardly extending arm 374 connected by a link 375 to a similar arm 376 secured to a transverse rock shaft 377 near one of its ends.

This rock shaft is mounted in the upper left 55 front part of the machine, the other end of this rock shaft has secured to it an arm 378 to which is pivoted one end of a connecting link or hook 379 the other end of which engages a pin 380 on the operating frame 122, 60 as best shown in Figs. 6, 7 and 26.

A spring 381 one end of which is secured 65 to the link 379 and the other end to a stationary part of the machine tends to normally hold the restoring lever 373 in its inoperative

This construction permits the operating frame 122 to move forward from its normal position and back to within a short distance of the end of its downward or rearward movement without affecting the restoring frame or lever 373, as during this movement the pin 380 on the operating frame 122 is free to move away from the hook 379, but during the last portion of this downward movement the pin engages said hook and swings the restoring frame 373 forwardly forcing the central locking bar 372 forward and unlocking all the identifying shifting keys of the said row. As the operating frame 122 again moves upwardly a short distance to its normal position the restoring frame is moved to its normal or retracted position by the action of its spring 381.

Identifying shifting key lock

A column locking device 383, (Fig. 20), as described in connection with the number setting keys, is employed for the row of special shifting keys, to enable any one of said keys to be permanently locked down to continually repeat its controlling effect as long as the locking device is in its depressed position.

Interlocks between various keys

The column of identifying shifting keys comprises two groups, one group of which is connected with a locking or single key system which prevents more than one of the keys comprising said group from being depressed 100 at a time, but allows the depression of one or more of the shifting keys in the other group not connected with the locking system at the same time that one key is depressed in the group which is connected with the blocking 105 system.

The mechanism whereby only one key of one group, which may be called the "total key" group, can be depressed at a time, and whereby certain other keys are locked against depression when any one of the first group of keys is depressed, and whereby all of this total key group are locked against depression when either one of the certain other keys is depressed, is constructed as follows: 400 represents links each pivoted at its rear end to the upright arm 395 or 506 of one of a series of lower elbow levers connected to the total keys 364, 365, 366, 367 and 368 and the key 363 as well as the key 337, shown in Figs. 6, 7 and 35.

The links 400 are each provided near their front end with a slot 401 through which passes a rod 402 upon which they are mounted to slide and which rod is secured at its opposite ends to two of the frames. On its extreme forward end each link 400 is provided with a circular wedge like enlargement or button 403. Mounted on the rod 402 between each pair of links 400 is a wedge shape button 404 constructed to be free to 130

slide on said rod. Immovably secured to said rod 402, on the outside of the two end links 400, are two wedge shaped buttons 405 and 406 (Fig. 8); the latter are positioned on said 5 rod a distance apart sufficient to allow only one of said wedge shape enlargements 403 to enter between the row of buttons 404 in addition to said links 400, as shown in Fig. 8. When any total key 364, 365, 366, 367 or 368 10 or the key 363 or the key 337 is depressed it rocks its lower elbow lever 395 or 506 as will be described, and its link 400 is drawn rearwardly forcing its wedge shape button 403 on the end of its link 400 into the space between 15 said buttons 404, as shown in Fig. 8, and fills all the available space between said buttons. If it is then attempted to depress any other of said keys, its button 404 will be blocked against rearward movement and such key 20 will be thereby blocked against depression.

The connections from the various shifting keys to the lower elbow levers 395 and 506 are best shown in Figs. 6 and 35. Taking key 367 for example it will be seen that upon 25 depression it will rock an elbow lever 392-393, pivoted on a rock shaft 391, while a link 394 connecting the lower end of arm 393 with the upper end of arm 395 of the lower elbow lever will serve to cause rocking 30 of the latter. Referring to Fig. 35 it will be seen that the connections from key 363 to the lower elbow lever are substantially the same but include an extra link and lever. Thus depression of the key 363 will rock the 35 shaft 485 by means of arm 486 and this will cause the arm 502, secured to the shaft, to draw rearwardly on link 518 and thereby rock an arm 503. Another link 505 connects this arm with the upper end of lower elbow 40 lever 506 to rock the latter. It will be noted that the link 518 is slotted to form its connection with the arm 502. This is to permit movement of the link 518 independently of arm 502 at a time when the link is shifted 45 by means of bell crank 519, 520 which is rocked upon depression of the key 362 and is connected to the link by pin and slot connection as at 522 (Fig. 7).

Means are provided whereby the number 50 keys are locked against depression when a total or another special key is depressed, and whereby these keys are locked against depression if any number key is depressed.

For this purpose also the column of identifying 55 keys is divided into two groups, one group of which is operatively connected with a device for locking the number setting keys, whereby the latter are locked against depression when any one of said shifting keys in 60 this group is depressed, but whereby the number keys are not affected if a key is depressed in the group not connected with the shift key locking device; and if any one of the number keys is depressed the shifting keys 65 in the group connected with the locking de-

vice are locked against operative depression while the shifting keys in the group not connected to the locking device are free to be depressed.

To permit of this action of these two groups 70 of identifying shift keys, relatively to the number keys the releasing bar for the identifying shift keys is made of two sections 370 and 371. The rear section 370 of this releasing bar is related to the identifying shift 75 keys 361, 337, 346 and 362 while the front section 371 is related to the identifying shift keys 363, 364, 365, 366, 367 and 368. A slack connection is provided between these sections 370 and 371 of this releasing bar which preferably consists of two hooks 465 and 466, arranged on the opposing ends of the releasing bar sections, and each hook is arranged with its bill loosely in the mouth of the other hook, so as to be capable of a limited longitudinal 80 movement one relatively to the other, as shown in Figs. 2, 7 and 20.

When all of the identifying shift keys are raised in their inoperative positions both 85 releasing bar sections 370 and 371 are in their rearward positions, as shown in Fig. 2.

Upon depressing one of the identifying shift keys 363, 364, 365, 366, 367 or 368 of the front group the front releasing bar section 371 is moved forwardly, as shown in Fig. 7, thereby operating a transverse locking bar 410 Fig. 12 for preventing depression of the number keys, and at the same time the front releasing bar section 371 pulls the rear releasing bar section 370 forwardly, thereby causing the companion pawl 261 to be raised and permit the associated locking bar 372 to move backwardly and lock the key in its depressed position.

If, however, one of the identifying shift keys 361, 337, 346 and 362 in the rear group is depressed only the rear section 370 of the releasing bar associated with these keys is moved forward, independently of the front section 371, as shown in Fig. 20, whereby the pawl 261 is released as before described for permitting the locking bar 372 to move rearwardly to lock said key in the depressed position, but the number keys are not locked and are free to be depressed, thereby permitting the printing of identifying characters either in connection with or independent of the numbers represented by the number keys.

At the end of the operation of the machine one or both sections of the releasing bar are moved backwardly into their normal position by the related spring 257.

The means whereby the number keys are locked against depression when the lower group of shift keys is depressed, and whereby the total and rule keys are locked against depression if any number key is depressed, are constructed as follows:

The release bar 371, Fig. 20, of the keys 130

364, 365, 366, 367, 368 and 363 is provided with a lug 407 which is adapted to engage the arm 408 of an elbow lever pivoted on the upper side of the lower key guide plate 213; the rearwardly extending arm 409 of the elbow lever engages a cross-bar 410 which is provided near its ends with elongated openings 411 through which pins 412 pass and by which it is movably secured to the lower 5 guide plate 213; the plate 410 is provided at its rear side with slots 413, as shown in Fig. 12. The release bars 220, Fig. 19, of the number keys are provided with downwardly extending lugs 414, and the cross-bar is normally in position to allow the lugs 414 of the 10 number key release bars 220 to move freely into its slots 413. When, however, any one of the keys 364, 365, 366, 367, 368, and 363 is depressed the release bar 371 is moved 15 forwardly and the cross bar 410 is moved to the left through the medium of the elbow lever 408—409, and the plain or flat face 415 of the cross rod 410 is interposed into the path of the lug 414 of the number key release 20 bars 220, preventing the forward movement of the latter and the depression of any of the number keys 210. If, on the other hand, one of the number keys is depressed the lug 414 of its release bar 220 is moved into the slot 25 413 of the cross bar 410, with the side 416 of the slot 413 close to said lug 414 to prevent the movement of the bar 410 to the left, and as the depression of any one of the lower 30 group of shift keys moves this bar 410 to the left, the blocking of said bar by the depression of any number key prevents the depression of any one of said lower group of shift 35 keys. As the rear end 370 of the release bar is capable of forward movement independent of the front end 371 the remaining shift keys of the row are not affected by nor do they affect the depression of the number keys.

Means are provided for releasing the differential stop devices of the number keys when a total key is depressed

417 represents a universal releasing bar arranged transversely underneath the lower ends of the several releasing pawls or dogs 50 261 of the stop bars of the number keys. Said releasing bar 417 is secured at its opposite ends to the front ends of the rock arms 418 and 419 which in turn are pivoted at their rear ends on the right and left ends of the 55 rod or shaft 263, as shown in Figs. 2, 3, 4, 5, 12, 14 and 16.

The left rock arm 419 forms an elbow lever with a depending rock arm 420 which latter is connected by a rod 421 with an ear 422 on 60 the left end of the elbow lever 408, as shown in Figs. 2 and 12.

As the front section 371 of the shift key releasing bar is moved forwardly by the depression of any one of the lower group of 65 shifting keys and the arm 408 of the elbow

lever is turned forwardly, the universal releasing bar 417 is raised through the medium of the elbow lever 420 and rod 421 connecting the same with the elbow lever 408, whereby all the number key stop bars will be released 70 from the pawls 261 preparatory to operating the machine.

During the initial portion of the subsequent operation of the machine the universal bar 266 releases the detainer pawls or dogs 75 264 from all of the number key stop bars 218, permitting the latter to be moved simultaneously forward, whereby the several differential stop arms 35 are permitted to rise with the operating frame rod 112 in advance of the forward movement of the gear segments 80 25, so that the latter are not arrested by the differential stops.

When the depressed shift key is again released and permitted to rise and release bar 85 section 371 is moved rearwardly into its normal position, the elbow lever 408, 409 is also moved backwardly and the universal bar 417 is depressed, thereby permitting the releasing dogs or pawls 261 to descend and re-engage 90 the shoulders of the number key stop bars 218 when the latter are moved rearwardly preparatory to the next operation of the machine.

Special interlock between two keys

In view of the particular functions which two of the special shifting keys are designed to control, it has been found desirable in accordance with the present invention to provide a special form of interlock between these keys. So far as the subject matter of this divisional case is concerned it will not be necessary to explain the particular functions which the keys are intended to control 100 but it will be sufficient to point out the mode of operation of the special interlock. In order to distinguish between the two keys they may be designated as the subtracting key which is key 337 and the total transfer key 105 which is key 366. The construction of the interlock is such that depression of the subtracting key will block the total transfer key and prevent its subsequent depression. However, if the total transfer key is first depressed the subtracting key may be subsequently depressed. Furthermore the interlock is such that both keys may be depressed simultaneously. By means of connections to the single-key mechanism, previously described, the depression of the subtracting key 110 337 will also block the subsequent depression of any of the other keys of the total key group.

443 represents a rock arm journaled concentrically with the upper arm 444 of the lower elbow lever which connects with the total transfer key 366, is arranged in rear of a lug 462 on said lever 444 and connected with a spreading rod 446 which is adapted to move 115 120 125 130

between two adjacent locking disks or members of the blocking mechanism, as best shown in Fig. 32.

447 represents a sleeve journaled on the shaft 448 of the transferring mechanism and provided with two depending arms 449, 450, one of which is connected with the blocking arm 443 by a front link 451 while the other is connected with the lower arm 340 of the upper subtracting lever by a link 452, as shown in Fig. 32.

453 and 454 represent the two depending arms of an elbow shaped locking lever which is pivoted for convenience on the adjacent rod or shaft 455 and the weight of its arm 454 tends to constantly turn it downwardly.

The rear arm 453 of the locking lever engages with a pin or shoulder 456 on the link 452 while the front arm 454 is provided with a curved row of locking teeth 457 which are adapted to be engaged by a locking shoulder 458 on a depending locking arm 459 which is secured to the shaft 448 of the total transfer mechanism. The locking teeth are arranged eccentrically with the arm 454 on which they are mounted but concentrically with the arm 459 which carries the co-operating locking shoulder 458.

This construction will be seen to prevent the setting of the total transfer key 366 subsequent to the setting of the subtraction key 337, since the rearward movement of bar 452 incident to the setting of the subtraction key withdraws pin 456 from arm 453, permitting arm 454 to drop until its teeth 457 engage the shoulder 458 of the total transfer mechanism lever 459, preventing movement of this lever. By providing a plurality of teeth 457 the depression of the subtracting key locks the total transfer key when the subtracting key has been only partially depressed. When, however, the total transfer key 366 is depressed first, the shoulder 458 is swung upwardly, clear of the teeth 457, and thereafter the subtracting key 337 can be depressed, without interference from the total transfer key mechanism. A slight slack connection is preferably provided between the subtracting key and the link 339 by such means as a pin 460 and slot 461, Fig. 32, so that if the total transfer key and subtracting key are depressed simultaneously the movement of the total transfer key will become effective in advance of the subtracting key, thereby preserving the proper order in which the parts controlled by these keys respectively perform their functions.

The subtracting key locks total keys

As the total transfer key 366 is depressed the lug 462 on the upper arm 444 of the lower elbow lever moves the arm 443 and the locking rod 446 backwardly so that the remaining total keys are locked against depression. This movement does not affect the subtract-

ing key owing to the pin-and-slot connection 463-464 between the link 451 and the arm 443, as shown in Fig. 32. If, however, the subtracting key only is depressed (for the ordinary subtraction operation) then the link 451 pulls the arm 443 and the locking bar 446 rearwardly, whereby the keys 362, 363, 364, 365, 367 and 368 associated with the locking blocks are locked against depression at the same time that the transferring key is locked against depression by the teeth 457, as has been described.

Special lock for shifting key

Referring particularly to Figs. 2, 7 and 33 it will be seen that means may be provided for locking certain of the shift keys, such as 346 and 362, in depressed position until manually released. Suitable means for this purpose may comprise a latch 523 pivoted at 524 on the under side of the upper guide plate 212 and provided with a hook 525 adapted to engage a slot 526 in the key stem, and having a finger piece 527 projecting through an elongated slot 528 in the guide plate 212.

Universal correction key

A universal correction or key restoring key 607 is provided, preferably at the foot of the row of shifting keys, for the purpose of restoring at one time all the keys that may have been depressed or set. The mechanism whereby the depression of this key is caused to restore any depressed shifting or number keys is constructed as follows:—

608 represents a rock arm mounted loosely on the shaft 377 and connected by a link 609 with a rock arm 610 which is secured to the rock shaft 241 within the arch shaped restoring arm 373 for the shifting keys, said arms 608 and 610 and link 609 being adjacent to the arms 376 and 374 and link 375 heretofore described, as best shown in Figs. 7, 12, 13 and 26.

611 represents a hub mounted loosely on the shaft 377 and provided with a forwardly projecting arm 612 which is engaged by the lower end of the shank of the correction key 607 and a forwardly and laterally projecting finger 613 fixed to said hub 611 extends across the front upper side of the rock arms 376 and 608.

When the correction key 607 is elevated the rock arms 376 and 608 and connecting parts are free to move independently of each other while restoring the number keys before the operation of the machine has been completed and while restoring the shifting keys at the end of the operation of the machine.

When it is desired to restore all of the keys which have been depressed without operating the machine for the purpose of setting another number or making a general correction it is only necessary to depress the correction key 607, the movement of which is transmitted by the arm 612 to the finger 613 where-

by the latter depresses both rock arms 376 and 608 simultaneously and causes them to swing the frame 373 and the universal restoring bar 245 forward, thereby drawing the 5 lock bars 219 forward and releasing all the keys depressed.

The driving mechanism

Reference has been made hereinbefore to 10 the main shaft 108 of the machine and to the fact that means are provided for releasing this shaft for operation so that a spring motor may drive the calculating mechanism. Since the spring motor and the means for winding it 15 form no part of the invention which it is intended to cover in this application it will not be necessary to discuss any of the details of this mechanism here but reference may be had to the parent application for a full disclosure. 20 However, the train of connections which are employed for releasing the main shaft so that it may be driven by the spring motor cooperate to a certain extent with the keyboard mechanisms so that these connections will now 25 be briefly described.

Referring particularly to Figs. 10 and 11 it will be noted that the machine is provided with three operating or release keys 753, 754, and 755 and also with an operating handle 30 614. All four of these operating elements are provided with suitable connections for releasing the main drive shaft of the machine. Secured to the shaft 108 is a stop disc 109 which is provided with a shoulder 692. This 35 shoulder is normally engaged by a shoulder 691 formed on a downwardly extending stop dog or arm 690. It will be apparent that in order to release the machine for operation it is only necessary to rock the arm 690 so that 40 its shoulder will be disengaged from the shoulder on the disc 109. A link or releasing rod 694 is provided with a hook 695 which is adapted to cooperate with the lower end of arm 690 and a spring 693 connected to this 45 link normally tends to hold the hook 695 in engagement with the arm. The forward end of link 694 is connected to a downwardly extending rock arm 697 pivoted on one of the supporting frame members while an upward- 50 ly extending arm 698 is adapted to move in unison with the lower arm. At the upper end of arm 698 is pivotally connected a link 699 which at the rear is connected to a depending trip arm 700 which is integral with the arm 55 269 which has already been mentioned. Also integral or rigidly connected with the arm 700 is a forwardly extending arm 777 which has an over-turned finger extending below a finger or lug 762 carried by an arm 761 of a 60 three-armed member pivoted on a stud 760. Suitable connections are provided from each of the three operating keys 753, 754 and 755 for the purpose of rocking this three arms member and hence rocking the arm 700. The 65 connections from key 753 comprise an arm

759 to which the stem 756 of the key is connected. Depression of the key will rock the arm 759 downwardly and through contact of its lower edge with the lug 762 of the three-armed member the latter will be rocked clockwise 70 thereby rocking the arm 777 and arm 700 counter-clockwise, Figs. 10 and 11, drawing the link 699 toward the rear and the hooked link 694 toward the front of the machine. This operation therefore will normally serve 75 to withdraw the shoulder of arm 690 from the shoulder 692 of disc 109 and thereby release the machine.

The connections from key 754 for rocking the three armed member to release the machine comprise a bell crank 765, 766 one arm of which is connected to the stem 757 of the key. The other arm of this bell crank is connected by a link 767 to a downwardly extending arm 763 of the three-armed member. In 80 order to permit rocking of the three-armed member independently of any movement of the link 767 a pin and slot connection 768, 769 is provided between the link and the arm 763. Somewhat similar connections are 85 provided between the operating key 755, which as will be explained more fully herein-after may be termed the repeat operating key, and the three-armed releasing member. Specifically these connections include a bell 90 crank 770, 771 pivoted on a stud 904 and one arm of which is connected to the stem 758 of the key. The other arm of the bell crank is connected by means of a link 772 through a pin and slot connection with the arm 763 of 95 the three-armed member. It will, therefore, be apparent that depression of any one of the three operating keys will serve to release the machine. In addition to these releasing connections the handle 614 shown in Fig. 10 100 and which is mounted on the shaft 615 is adapted to release the machine. The connections for this purpose comprise a sector 679 secured to the shaft 615, the sector being provided with a cam 702 facing radially toward the shaft 615. This cam is adapted to cooperate with a roller 701 mounted on an arm 705 which is connected to the arm 700. Movement of the segment 679 by operation 105 of handle 614 will therefore cause the roller 110 701 to be cammed rearwardly and through its connection with the arm 700 will rock the latter counter clockwise to effect release of the main shaft.

The function of the arm 269 which is 120 rocked with the arm 700 has already been explained in connection with the releasing and locking mechanism of the keyboard.

Repeating operating key

125

Means are provided whereby upon depressing the repeating operating key 755 the number set up on the number keys may be repeatedly added and printed with one setting up of said numbers. 130

The mechanism for this purpose is constructed as follows:

904 represents a transverse rock shaft which is journaled in the frame below the keyboard and to the right end of which the repeating operating key lever 770 is secured, as shown in Figs. 10, 4 and 5. To the left end of this shaft is secured a depending rock arm 905 which latter is connected by a link 906 with the coupling link 250 of the number key releasing mechanism. The lower end of the coupling link 250 is provided with a shoulder or hook 907 which is normally held in engagement with the rock arm 248 by a spring 908, so that when a number set up on the keyboard is to be added and printed but once, the arm 248 being lifted by the arm 123 of the operating frame during the last part of its forward movement, the numeral keys are released by the mechanism comprising link 250, rock arms 251 and 271, shaft 241 and bail 245, in the manner heretofore explained. When however the repeating operating key is depressed after the number has been set up, the link 906 will be moved forwardly, moving the arm 250 with its hook or shoulder 907 forwardly and out of the path of the pin 909 on the rock arm 248, so that when the latter rises during the operation of the machine the link 250 is not raised and the numeral keys remain set. Whenever the coupling link 250 is thus moved into its inoperative position it is held in this position during the forward movement of the operating mechanism by a detent pawl or latch 910 pivoted on the frame above the rock arm 248 and adapted to engage with a pin or shoulder 911 on the coupling link 250, the spring 908 operating to move the detent pawl into its operative position.

After the machine has effected the initial portion of its operation and the pin 909 of the rock arm 248 has passed above the shoulder or hook 907 of the coupling link 250 then a lug or finger 912 on the rock arm 248 engages the detent pawl or latch 910 and lifts the same out of engagement from the pin 911 on the coupling link 250, thereby releasing the coupling link and permitting the same to automatically reengage its hook or shoulder 907 with the rock arm 248 when the latter again reaches the end of its return or downward stroke, whereby the parts are restored to a condition in which the number keys are released at the end of the operation of the machine, but the number keys have not been released during this operation and remain set for the next operation. By depressing the repeat operating key 755 repeatedly the same number will be added and printed repeatedly as often as desired.

In order to permit the repeating operating key to rise immediately after the same has been depressed a slack connection is placed in the train of mechanism connecting its lever

with the coupling link 250, this slack connection preferably consisting of a pin 913 on the coupling link 250 engaging with a slot 914 in the front end of the intermediate link 906, as shown in Figs. 4, 5, and 10. 70

When the repeating operating key is depressed it not only throws out the coupling link so as to retain the set number keys in their depressed position, but at the same time the detent latch or dog 690 of the motor is released, in the manner already described. 75

Division indicating bar

For the purpose of indicating on the keyboard any desired divisions of the latter which may be employed at a given time the present invention contemplates the use of keyboard dividing bars. Frequently it is desired to divide the keyboard in accordance with the monetary system so as to distinguish readily between dollars and cents whereas at other times it may be desired to divide the keyboard in accordance with the straight decimal system. With this in mind as well as the possibility of dividing other units of the calculating machine, as more fully explained in the parent application, the keyboard dividing or indicating bars 1388 are adapted to be removably inserted in any pair of sockets 1390 located at the front and rear of the keyboard between each pair of rows of keys, as best shown in Fig. 1. The particular construction of the indicating bars is best shown in Fig. 25 from which it may be seen that downwardly extending pins 1389 formed on the bars are adapted to engage with the openings or sockets 1390 in the keyboard. 95

Supplementary typewriting mechanism

Mention has already been made of the fact that the calculating mechanism of the present invention is to be used in combination with suitable typewriting mechanism. The construction is such that the calculating mechanism is removably supported in the frame which carries the typewriting mechanism and it is located between the typewriting keys and the printing elements controlled by these keys. The arrangement of the two mechanisms is best shown in Fig. 27 to which reference may be made in connection with the following detailed description: 100

A plurality of type bars 1601a are arranged above and in rear of a platen 148 and pivoted at their rear ends to swing vertically for moving the letter type 1602 at their front end toward and from the upper side of the platen. A plurality of rear elbow levers are arranged in rear of the platen and are pivoted on the rod 1603 secured in the lower rear part of a supplemental frame 1604 to swing vertically. Each elbow lever has an upwardly projecting rear arm 1605 which is connected by a link 1606 with a tail 1607 on 115 120 125 130

its respective type bar, and a forwardly projecting front arm 1608. A plurality of front levers 1609 are pivoted on a rod 1610 to swing vertically, and each has its rear arm 1611 engaging with the lower front arm 1608 of one of the rear elbow levers. A plurality of upright vertically movable letter type keys 1612 are arranged in front of and below the number setting keys 210, and each has the lower end of its shank connected with the front arm of one of the front levers 1609, as shown in Fig. 27.

Normally the type bars 1601a are raised into their inoperative position by springs 1613 and the levers 1609 are thereby turned so as to raise the letter keys 1612. Upon depressing any one of said letter keys its corresponding letter type bar 1601a is depressed and delivers a blow of its type 1602 against the platen, leaving an impression on the paper or record sheet supported thereon.

Typewriter keys locked when adding mechanism is operated

25 Means are provided for preventing the typewriting keys from being depressed while the adding mechanism is being operated, thereby preventing conflict between the two separate mechanisms. The means for this purpose, shown in Figs. 27 and 30, are constructed as follows:

1614 represents a universal rod or bar arranged transversely over the rear arms 1611 of the front rock levers and supported at opposite ends by rock arms 1615 and 1616. A catch 1618, pivoted on the base of the supplemental frame 1604, is adapted to swing into and out of engagement with the universal rod 1614, and when free is moved by a spring 1617 forwardly into engagement with said rod 1614 for holding it in its depressed position and the letter keys 1612 in their elevated position. Cooperating with catch 1618 is a releasing elbow lever having a downwardly extending arm 1621 which terminates in a laterally extending finger 1622, located in front of the upper part of catch 1618. The forwardly extending arm 1620 of said elbow lever is provided with a transversely extending finger 1619, overlying a cam arm 957 which is actuated by a cam 959 on the main operating shaft 108. Finger 1619 is held in contact with arm 957 by spring 1623. When the machine is at rest (Fig. 27) a low part 55 of cam 959 stands opposite the arm 957, and the finger 1622 engages and displaces catch 1618, leaving the typewriter keys 1612 free. When, however, the cam 959 begins to turn and the calculating mechanism performs various functions according to the numbers set up on the number keys 210, then the releasing elbow lever 1620—1621 swings forward and allows the catch 1618 to engage the universal rod 1614 and thereby prevent the depression 60 of the typewriter keys 1612.

Typewriter key locks adding mechanism

Means are provided for preventing an adding and its printing operation of the adding machine from being performed while a typewriter key is depressed, thereby preventing improper printing on the platen. The means for this purpose are constructed as follows and shown in Figs. 27 and 31.

70 A rock lever comprising two arms 1624 and 1625 is secured to a shaft which is pivoted in bearings on the base of the adding machine; this rock lever engages its front arm 1625 with the rear end of the releasing hook 694 and its rear arm 1624 with a nose 1626 on one of the arms 1615 which support the universal rod 1614. Whenever a typewriter key 1612 is depressed the universal rod 1614 is raised and the intermediate lever 1624—1625 is turned in a direction which causes the hook 85 694 to be lowered out of engagement from the detent pawl or dog 690, as shown in Fig. 27, thereby preventing release of the motor and an adding operation when the operator at this time depresses an operating key or 90 lever.

Means for preventing operation of typewriter keys after effective operation of adding machine

95 Due to the fact that the printing elements of the calculating machine as well as of the typewriter mechanism cooperate with the same platen and are designed to produce a continuous record on a record sheet placed in the machine, as more fully explained in the parent application, it becomes necessary to provide certain safety devices to prevent confusion between the matter printed by the separate recording mechanisms. For example, if after a number has been printed by the calculating machine printing mechanism the typewriter keys should be free to be operated they would effect printing directly over the number previously printed. However, if 100 the record material has been shifted to a new column so that there is no danger of conflict between the matter recorded by the two mechanisms, the need for locking up the typewriter keys is dispensed with. Various means are 105 described in the parent application for controlling the effectiveness of the lock for the typewriter keys upon operations of the calculating mechanism. We are concerned in this divisional application with only two of these 110 means, one through which the effectiveness of the lock is controlled by the amount keyboard of the calculating machine and the other through which effectiveness is controlled by a special key. Considering the first of 115 these means it will be apparent that an operation of the calculating machine in which no amount keys are depressed will not result in the making of any record on a record sheet 120 and that therefore there is no need for locking 125

up the typewriter keys after such an idle operation. This of course assumes that the record sheet was clear at the time of this idle operation or had been shifted in some way 5 after the last recording operation. It has already been explained how during an operation of the adding machine the typewriter keys become locked due to the rocking of the arm 1621 which then permits the hook 1618 10 to engage the cross bar 1614 which in turn prevents depression of any of the keys 1612. Connected to the forward end of the arm 1620 of the bell crank 1620, 1621, which is rocked by means of the cam 959, is an upwardly extending 15 detent bar 1662 which is urged rearwardly against a pin 1663 by means of a spring 1664. Pivoted upon the detent bar is a detaining pawl 1665 which is urged toward the rear of the machine by means of a spring 20 also carried by the bar 1662. Now as the arm 1620 is rocked counter clockwise by an operation of the adding machine the pawl 1665 will be carried above the pin 1663 and will normally be latched over the latter. This therefore, if not otherwise affected, would result 25 in maintaining the bell crank 1620, 1621 in rocked position at the termination of the operation of the machine so that the typewriter keys would remain locked. However, the upper 30 end of the bar 1662 is provided with a cam face 1677 which cooperates with a lug or shoulder on a downwardly extending arm 1674 which is pivoted on the shaft 263 and is controlled by the keys of the computing machine 35 keyboard. In the normal position of the arm 1674 its lower end will be in the path of the cam surface 1677 so that as the bar 1662 is raised it will simultaneously be rocked forwardly so that the pawl 1665 will be prevented 40 from latching over the pin 1663.

The control from the bank of shifting keys over the action of bar 1662 is effected through a finger 1675 formed on the arm 1674 and which engages the upper edge of one of the 45 arms 262 of the releasing dog 261 associated with this bank. It will be recalled that this dog is lifted upon depression of any key in the bank of shifting keys. A finger 1676 Fig. 28 formed on a downwardly extending 50 arm 556 of the bail member 555 furthermore engages the rear edge of arm 1674 to swing the latter whenever the bail 555 is lifted. This bail as will be remembered extends across the entire set of releasing dogs 261 associated 55 with the amount key banks so that lifting of anyone of these dogs will lift the bail. It will therefore be clear that whenever an amount key or special shift key is depressed the arm 1674 will be rocked into the dotted 60 line position of Fig. 27 wherein it will be out of the path of the cam surface 1677 of bar 1662. Under this condition the pawl 1665 will become latched over the pin 1663 as the bar rises and hence the typewriter keys will 65 be maintained in locked condition after the

completion of the operation of the machine. However if the arm 1674 remains in its normal or full line position of Fig. 27, as when no key is depressed, the lower end of the arm will serve to cam the bar 1662 forwardly as 70 the latter rises and the pawl 1665 will be prevented from engaging the pin 1663. Therefore an idle operation of the machine does not tend to leave the typewriter keys in locked condition. 75

Key for releasing typewriter keys

If it is desired to release the typewriter keys for such purposes as continuing the typewriting in close proximity to a number consisting of a less number of figures than would fill the space corresponding to the width of a column, or to write over the numbers previously printed as for instance when the number is to be erased and the carriage has not been moved then the typewriting mechanism may be deliberately made operative while the number printed is in the printing position of the letter type bars. For this purpose a releasing key lever 1670 is provided adjacent to the letter key levers, a key button arranged on the front arm of the restoring key lever 1670, an intermediate rock arm 1671 engaging with the rear arm of the restoring key lever, an upright link 1672 connected at its lower end with the rock arm 1671, and a rearwardly projecting rock arm 1673 connected with the upper arm 1668 and also connected loosely with the upper end of the link 1672, as shown in Figs. 27 and 31. Let it be assumed that a number has been printed by the operation of the adding mechanism, and that the typewriter keys have been locked by reason of the detent bar 1622 engaging with its dog 1665 over the rod 1663 while in its elevated position, the dog 1618 being hooked over the universal bar 1614. If it is desired to print over the numbers for cancelling the same, this can be accomplished by first depressing the releasing or restoring key 1670, which movement is transmitted successively by the lever arm 1670—1671, link 1672, arms 1673 and 1668, and link 1669, to the detent 1662, and disengages the dog 1665 of the latter from the rod 1663. The arm 1621 is permitted to be drawn rearwardly by its spring and the weight of the detent 1662, and the dog 1618 is forced rearwardly out of engagement with the universal rod 1614, thereby permitting the typewriting mechanism to be operated notwithstanding that the printing position of its type bars is over the number printed on the record sheet. Other controls for the detent 1662, not included in this divisional case, are described in the parent patent, herefore identified. 100

The foregoing description and the drawings, are to be understood as merely illustrating typical embodiments of inventions 110 115 120 125 130

which may take a variety of other forms, all falling within the scope of the appended claims, which are to be broadly construed.

What is claimed is:

5. 1. In a calculating machine, the combination of a plurality of rows of keys, each provided with a stem, upper and lower guide plates through which the stems of the keys pass, means for yieldingly holding the keys
 10 in an elevated position consisting of a rod arranged on the underside of the lower plate between adjacent rows of key stems, and springs arranged on said rod and each having its ends connected with the lower ends of
 15 two key stems.
2. In a calculating machine, the combination of a plurality of rows of setting keys each having a stem, a stop bar arranged adjacent to each row of keys and provided with
 20 stop lugs adapted to engage with the stems thereof and also provided with a releasing tooth, a releasing dog engaging with the releasing tooth, and a releasing bar provided with an incline which engages with said releasing dog and with a plurality of inclines which are engaged by said key stems.
3. In a calculating machine, the combination of a plurality of rows of setting keys each having a stem, a stop bar arranged adjacent to each row of keys and provided with a plurality of stop lugs, one associated with each key and adapted to engage with the stem thereof, and a bodily movable locking bar arranged adjacent to each row of keys and provided with a plurality of hooks associated respectively with and adapted to engage the stems of the keys.
4. In a calculating machine, the combination of a plurality of rows of setting keys each having a stem, a stop bar arranged adjacent to each row of keys and provided with a plurality of stop lugs, one associated with each key and adapted to engage with the stem thereof, and a locking bar arranged adjacent to each row of keys and provided with hooks adapted to engage with the stems of the keys, the bills of said hooks having inclined front ends and abrupt upper sides for engagement with said stems.
- 50 5. In a calculating machine, the combination of a plurality of rows of setting keys each having a stem, a stop bar for each row of keys having a releasing tooth and a plurality of stop lugs, one associated with each key for engaging the stem thereof, a releasing dog engaging said releasing tooth, a releasing bar for each row of keys having inclines adapted to be engaged by said stems and a releasing cam adapted to engage said releasing dog, and a locking bar having hooks adapted to engage said key stems.
- 60 6. In a calculating machine, the combination of a plurality of rows of setting keys each having a stem, a stop bar for each row of keys having stop lugs for engaging the stems

of the keys and a releasing tooth, a releasing dog engaging said releasing tooth, a releasing bar for each row of keys having inclines adapted to be engaged by said stems and a releasing cam adapted to engage said releasing dog, a locking bar having hooks adapted to engage said key stems, and a universal stop adapted to arrest the locking movement of said locking bar.

7. In a calculating machine, the combination of a plurality of rows of setting keys each having a stem, a stop bar for each row of keys having stop lugs for engaging the stems of the keys and a releasing tooth, a releasing dog engaging said releasing tooth, a releasing bar for each row of keys having inclines adapted to be engaged by said stems and a releasing cam adapted to engage said releasing dog, a locking bar having hooks adapted to engage said key stems, a universal stop adapted to arrest the locking movement of said locking bar, and a universal restoring bar adapted to engage with lugs on said locking bar.

8. In a calculating machine, the combination of a plurality of rows of setting keys each having a stem, a stop bar for each row of keys, a locking bar for each row of keys having a plurality of locking hooks which are provided with inclined faces adapted to be engaged by said keys, means urging said bar into locking position, and a tension device which acts upon said locking bar to resist its key unlocking movement.

9. In a calculating machine, the combination of a plurality of rows of setting keys each having a stem, a stop bar for each row of keys, a locking bar for each row of keys having a plurality of locking hooks which are provided with inclined faces adapted to be engaged by said keys, a tension device which acts upon said locking bar and which consists of a rocking tension arm having a shoulder adapted to engage with said locking bar, a spring operating to hold the tension arm against said locking bar, and a universal restoring arm adapted to engage with a lug on the tension arm for disengaging the shoulder of the latter from the locking bar.

10. In a calculating machine, the combination of a plurality of rows of setting keys, and means for causing an increased resistance to the depression of a second key after the depression of the first key in each row.

11. In a calculating machine, the combination of a plurality of rows of setting keys, means which comes in operation after the first depression of one key in a row for causing an increased resistance to the subsequent depression of another key in the same row, and a restoring device for said means.

12. In a calculating machine, the combination of a plurality of rows of setting keys, a resistance device which is inoperative upon the first depression of any one key in a row

but which becomes operative and increases the resistance to the subsequent depression of another key in the same row, and means for rendering said resistance device operative or 5 inoperative.

13. In a calculating machine, the combination of a plurality of rows of setting keys, a stop bar for each row of keys, a locking bar for each row of keys having hooks with inclined ends for co-operating with the respective keys, a plurality of resistance or tension arms each having a shoulder adapted to engage with a shoulder on one of said locking bars, a spring operating to hold each resistance or tension arm in its active position, and 15 a universal shifting bar adapted to move the several resistance or tension arms into an inactive position.

14. In a calculating machine, the combination of a plurality of rows of setting keys, a stop bar for each row of keys, a locking bar for each row of keys having hooks with inclined ends for co-operating with the respective keys, a plurality of resistance or tension 25 arms each having a shoulder adapted to engage with a shoulder on one of said locking bars, a spring operating to hold each resistance or tension arm in its active position, a universal shifting bar adapted to move the 30 several resistance or tension arms into an inactive position, and a shifting key for controlling the position of said universal bar.

15. In a calculating machine, the combination of a keyboard having a plurality of rows 35 of keys, a device for resisting the depression of the keys, and means for increasing the resistance to the depression of the keys, said means being movable from effective position to ineffective position at the will of the operator.

16. In a calculating machine, the combination of a keyboard having a plurality of rows of setting keys, and means for locking a depressed key in a row, said means being capable of either locking or not locking the remaining keys in the same row in an elevated position.

17. In a calculating machine, the combination of a main operating frame, a keyboard 50 having a plurality of rows of setting keys, a correction key for each row of setting keys, means operating to lock the correction keys during the initial portion of the forward movement of said operating frame, and means operating to release the correction keys before completion of the forward movement of said operating frame.

18. In a calculating machine, the combination of a keyboard having a plurality of rows 60 of keys, a stop bar for each of said rows of keys, a locking bar for each of said rows of keys, a universal stop bar for said locking bars, and means for moving said universal stop bar into or out of operative relation to said locking bars.

19. In a calculating machine, the combination of a keyboard having a plurality of rows of keys, a stop bar for each row of keys having stop shoulders for co-operation therewith and a releasing shoulder, a locking bar for each row of keys having hooks for co-operation therewith and a plurality of stop shoulders, a spring for moving each locking bar backwardly, releasing dogs for engaging the releasing shoulder of each stop bar and one of the shoulders of the locking bar, a universal stop bar adapted to be engaged by the other shoulder of each locking bar, and a shifting key connected with the universal stop bar and capable of moving the same into an operative or inoperative position relative to said shoulders. 70

20. In a calculating machine, the combination of a plurality of numeral keys, a plurality of shifting keys, a locking device constructed to permit of holding any one of the shifting keys in its depressed or operative position, an operating frame having a forward and backward movement, means under control of said frame for locking and releasing said numeral keys, and a connection between said frame and said locking device which operates to disengage said locking device from and release the depressed shifting key during the last part of the backward movement of the operating frame. 75

21. In a calculating machine comprising a plurality of depressible shifting keys, a locking bar provided with a shoulder and with hooks adapted to retain any key which is depressed, and an operating frame having a forward and backward movement; a connection between said operating frame and locking bar for disengaging the latter from the depressed key during the last part of the backward movement of the frame, said connection comprising a releasing lever having an arm adapted to engage with the locking bar shoulder to shift the locking bar to inoperative position, an intermediate rock shaft, arms arranged on the right and left parts of the rock shaft, a link which connects the left rock shaft arm with an arm of said releasing lever, a second link connected at one end with the right rock shaft arm, and a hook arranged on the opposite end of said last mentioned link engaging loosely with a pin or rod on the operating frame. 100

22. In a calculating machine, the combination of a plurality of number keys, a plurality of shifting keys, means for locking any one of the number keys in its depressed or operative position, means for locking any one of said shifting keys in its depressed or operative position, operating means including a pivoted frame having a plurality of extending arms, means operatively connected with one of said arms for disengaging said shifting key locking means from the depressed shifting key during the last part of the opera- 110

tion of the machine, and means operatively connected with another of said arms for disengaging said number key locking means from the depressed number key before the 5 shifting key has been released.

23. In a calculating machine, the combination of a plurality of number keys, a plurality of shifting keys, means for locking any one of the number keys in its depressed or operative 10 position, means for locking any one of said shifting keys in its depressed or operative position; an operating frame having a forward and backward movement, shifting key lock actuating means operatively connected with said frame and adapted to release the depressed shifting key during the last part of the backward movement of said frame, and a separate number key locking means operatively connected with the operating frame independently of the shifting key locking means and adapted to release the depressed number keys before the depressed shifting key is released.

24. In a calculating machine, the combination of a plurality of number keys, a number key locking bar for holding any one of said number keys in its depressed position, a plurality of shifting keys, a shifting key locking bar for holding any one of said shifting keys 30 in its depressed position, an operating mechanism including a frame having a plurality of extending arms, a connection between one of said arms and the shifting key locking bar whereby the latter is moved to release the depressed shifting key during the last part of the operation of the operating mechanism, and a separate connection between the operating mechanism and said number key locking bar whereby the latter is moved to release 35 the depressed number key before the release of the depressed shifting key is effected.

25. In a calculating machine, the combination of a plurality of numeral keys, a plurality of shifting keys arranged in a row 45 adjacent to a row of said numeral keys, a longitudinally movable locking bar constructed and operating to hold any one of said shifting keys in its depressed or operative position, an operating frame having 50 a forward and backward movement, a connection between said frame and said locking bar whereby the latter is moved in the direction of its length and the depressed key is released during the last part of the backward movement of the operating frame, and means for rendering said connection operative and inoperative.

26. In a calculating machine, the combination of a plurality of shifting keys, a locking bar constructed and operating to hold any one of said shifting keys in its depressed or operative position, an operating frame having a forward and backward movement, a connection between said frame and said 65 locking bar whereby the latter is shifted

and the depressed shifting key is released during the last part of the backward movement of the operating frame comprising a releasing lever loosely connected with said operating frame, a dog mounted on said locking bar and adapted to be engaged by said releasing lever, and a key whereby said dog may be shifted into and out of operative relation to said releasing lever. 70

27. In a calculating machine, the combination of the number keys, an identifying shift key mechanism, devices common to and controlled by all of the keys of said mechanism, and means operating to lock part of said shift key mechanism upon the depression of a number key and locking said number keys upon depressing said part of the identifying shift key mechanism, the other part of said identifying shift key mechanism being unaffected by the depression of a number key. 75

28. In a calculating machine, the combination of the number keys, two groups of identifying shift keys, controlling devices common to and operated by the keys of both 90 groups, and a reciprocal locking device operatively related to the number keys and one group of identifying keys, the other group of identifying shift keys having no locking relation to said number keys. 95

29. In a calculating machine, the combination of the number keys, a plurality of identifying shift keys comprising two groups, a releasing bar composed of two sections one section of which is operatively related to one of said groups of identifying shift keys while the other section is operatively related to the other group of shift keys, and a reciprocal locking device operatively associated with one section of said releasing bar and said number keys. 100

30. In a calculating machine, the combination of the number keys, a plurality of identifying shift keys comprising two groups, a releasing bar composed of two sections one section of which is operatively related to one of said groups of identifying shift keys while the other section is operatively related to the other group of shift keys, a reciprocal locking device operatively associated with one section of said releasing bar and said number keys, and a slack connection between said releasing bar sections. 110

31. In a calculating machine, the combination of the number keys, a plurality of identifying shift keys comprising two groups, a releasing bar composed of two sections one section of which is operatively related to one of said groups of identifying shift keys while the other section is operatively related to the other group of shift keys, a reciprocal locking device operatively associated with one section of said releasing bar and said number keys, and a slack connection between said releasing bar sections 120

125

130

- consisting of hooks arranged on the opposing ends of said releasing bar sections and each hook arranged with its bill in the mouth of the other hook so as to permit of a limited independent longitudinal movement of the releasing bar sections relative to each other.
32. In a calculating machine, the combination of a plurality of item keys, a plurality of shifting keys comprising two groups, each group including totalizer controlling keys, and a blocking device associated with one only of said groups and operating to prevent the depression of more than one key at a time in said group.
33. In a calculating machine, the combination of a plurality of item keys, a plurality of shifting keys comprising two groups, each group including totalizer controlling keys, and a blocking device associated with one only of said groups and operating to prevent the depression of more than one key at a time in said group while the keys in the other group are free to be depressed more than one at a time independent of said blocking device.
34. In a calculating machine, the combination of a plurality of item keys, a plurality of shifting keys comprising two groups, each group including totalizer controlling keys, and a blocking device associated with one of said groups and operating to prevent the depression of more than one key at a time in said group, the keys in other groups being unprovided with a blocking device so as to permit one or more of the last mentioned keys to be depressed simultaneously with one of the keys associated with the blocking device.
35. In a calculating machine, the combination of a plurality of number keys, a locking device for preventing the depression of said number keys, a plurality of shifting keys comprising two groups, controlling devices common to and operated by the keys of both groups, a locking device for one group of said shifting keys which prevents the depression of said last mentioned keys, and means whereby the depression of any number key prevents the depression of the group of shifting keys which are associated with said locking device.
36. In a calculating machine, the combination of a plurality of number keys, a locking device for preventing the depression of said number keys, a plurality of shifting keys comprising two groups, each group including totalizer controlling keys, controlling devices common to and operated by the keys of both groups, a locking device for one group of said shifting keys which prevents the depression of said last mentioned keys, and means whereby the depression of any key in the group of shift keys associated with said locking device causes the number keys to be locked against depression.
37. In a calculating machine, the combination of a plurality of number keys, a locking device for preventing the depression of said number keys, a plurality of shifting keys comprising two groups, controlling devices common to and operated by the keys of both groups a locking device for one group of said shifting keys and which prevents the depression of said last mentioned keys, means whereby the depression of any number key prevents the depression of the group of shifting keys which are associated with said locking device, and means whereby the depression of any key in the group of shift keys associated with said locking device causes the number keys to be locked against depressions.
38. In a calculating machine, the combination of a plurality of number keys, a locking device for said number keys, a plurality of shifting keys, a locking device for said shifting keys, an intermediate mechanism acting to lock said number keys when any one of said shifting keys is depressed and to lock said shifting keys when any one of said number keys is depressed, a plurality of shifting keys provided with a separate locking device not affected by said intermediate mechanism, and means whereby all of said number and shifting keys are locked during the operation of the machine.
39. In a calculating machine, the combination of a plurality of number keys, a locking device for said number keys, a plurality of shifting keys, a locking device for said shifting keys, a blocking device for said shifting keys to prevent more than one shifting key from being depressed at a time, and an intermediate mechanism acting to lock said number keys when any one of said shifting keys is depressed and to lock said shifting keys when any one of said number keys is depressed.
40. In a calculating machine, the combination of a plurality of number keys, a locking device for said number keys, a plurality of shifting keys, a locking device for said shifting keys, a blocking device for said shifting keys to prevent more than one shifting key from being depressed at a time, an intermediate mechanism acting to lock said number keys when any one of said shifting keys is depressed and to lock said shifting keys when any one of said number keys is depressed.
41. In a calculating machine, the combination of a plurality of number keys, a locking device for said number keys, a plurality of shifting keys, a locking device for said shifting keys, a blocking device for said shifting keys to prevent more than one shifting key from being depressed at a time, an intermediate mechanism acting to lock said number keys when any one of said shifting keys is depressed.

pressed and to lock said shifting keys when any one of said number keys is depressed, a plurality of shifting keys provided with a locking device which is not operatively connected with the intermediate mechanism, and means whereby all of said number and shifting keys are locked during the operation of the machine.

42. In a calculating machine, the combination of a plurality of number keys, a locking device for said number keys, a plurality of shifting keys, a locking device for said shifting keys, a blocking device for said shifting keys to prevent more than one shifting key from being depressed at a time, an intermediate mechanism acting to lock said number keys when any one of said shifting keys is depressed and to lock said shifting keys when any one of said number keys is depressed, and means whereby all of said number and shifting keys are locked during the operation of the machine.

43. In a calculating machine, the combination of number keys, means for retaining said keys when depressed, means for releasing the depressed keys, a shift key, means for retaining said shift key when depressed, means for releasing said shift key after said number keys have been released, a universal correction key, and means whereby both the number keys and the shift key may be simultaneously released by said universal correction key.

44. In a calculating machine, the combination of a row of number keys, a longitudinally movable locking bar adapted to engage with said keys and hold them in a depressed position, a row of shifting keys, a locking bar for holding said shifting keys in a depressed position, and a correction key arranged to move said locking bars for releasing said number keys and shifting keys.

45. In a calculating machine, the combination of a row of number keys, a longitudinally movable locking bar adapted to engage with said keys and hold them in a depressed position, a row of shifting keys, a locking bar for holding said shifting keys in a depressed position, means for releasing said number key locking bar, means for releasing the shifting key locking bar, and a correction key operatively related to both of said locking bar releasing means.

46. In a calculating machine, the combination of a row of number keys, a longitudinally movable locking bar adapted to engage with said keys and hold them in a depressed position, a row of shifting keys, a locking bar for holding said shifting keys in a depressed position, an operating mechanism, means for releasing said number key locking bar before the operation of the machine has been completed, means for releasing said shifting key locking bar at the end of the operation of the machine, and a correction

key operatively connected with the releasing means of both locking bars.

47. In a calculating machine, the combination of a plurality of rows of number keys, a locking bar for holding each row of number keys in their depressed position, a multiple releasing bar arranged to withdraw the several locking bars from the number keys, a row of identifying shifting keys, a locking bar for holding the identifying shifting keys in a depressed position, an individual releasing bar arranged to withdraw the locking bar from the identifying shifting keys, an operating mechanism, means for causing the multiple releasing bar to become operative before the operation of the machine has been completed, means for causing the individual releasing bar to become operative at the end of the operation of the machine, and a correction key arranged to simultaneously withdraw said multiple and individual releasing bars.

48. In a key-controlled machine, an upper and a lower plate secured together in spaced relation to one another and each provided with a row of recesses of which each upper and its corresponding lower recess constitute a key-way, a row of keys each having a stem extending through one of said key-ways, means for normally holding each key stem in its elevated position, a bar mounted for movement between the plates and correlated with the said keys for being stopped when one of the latter is depressed, means between said plates for engaging with the stems of the depressed keys for holding them depressed against action of their elevating means, and means between said plates and provided with suitable connections for releasing the depressed keys by the depression of another of said keys.

49. In a machine of the class described a plurality of rows of number keys, a plurality of special keys, means for latching any of said keys when operated, a main operating mechanism including a frame having a plurality of extending arms, and connections from said arms for releasing any operated keys, said special keys being released at a different time from said number keys.

50. In a machine of the class described a plurality of rows of number keys, a plurality of special keys, means for latching any of said keys when operated, a main operating mechanism comprising a plurality of extending arms, and connections from said arms for releasing any operated keys, said number keys being released prior to said special keys.

51. In a machine of the class described a plurality of rows of number keys, a plurality of special keys, means for latching any of said keys when operated, a main operating mechanism, connections from said mechanism for releasing any operated keys, said special keys being released at a different time from said number keys, and manual means

for simultaneously releasing all of said operated keys.

52. In a machine of the class described a plurality of rows of number keys, a plurality of special keys, means for latching any of said keys when operated, a main operating mechanism, connections from said mechanism for releasing any operated keys, said number keys being released prior to said special keys, 10 and manual means for simultaneously releasing all of said operated keys.

53. In a machine of the class described a plurality of settable manipulative devices, an operating mechanism, and means controlled 15 by said operating mechanism for preventing manipulation of said devices during the initial portion of an operation of said mechanism but permitting manipulation of said devices at substantially the middle of the 20 operation of said mechanism.

54. In a machine of the class described a plurality of rows of settable keys, a main operating mechanism, means for holding one or more of said keys when set, means operated 25 by said operating mechanism for releasing said keys, and means associated respectively with certain of said rows adapted to disable the releasing means for the row with which they are associated without disturbing 30 the relation between said releasing means and other of said rows of keys.

55. In a machine of the class described a plurality of rows of settable manipulative devices, means for detaining said devices in 35 set position when set, means for releasing said devices comprising members individual to each row of devices, a main operating mechanism and connections therefrom to all of said members for operating the latter, and 40 means associated respectively with certain of said rows for disabling said connections for the row with which they are associated without disturbing the connections to other of said rows.

45. 56. In a machine of the class described a plurality of rows of settable manipulative devices, means for detaining said devices in set position when set, means for releasing said devices comprising members individual 50 to each row of devices, a main operating mechanism and connections therefrom to all of said members for operating the latter, means associated respectively with certain of said rows for disabling said connections to 55 the one of said rows with which they are associated without disturbing the connections to other of said rows, and means for simultaneously disabling all of said connections.

57. In a machine of the class described a 60 plurality of rows of settable manipulative devices, means for detaining said devices in set position when set, means for releasing said devices comprising members individual to each row of devices, a main operating mechanism and connections therefrom to all

of said members for operating the latter, means for disabling said connections to one of said rows without disturbing the connections to other of said rows, and means for simultaneously disabling all of said connections, said last mentioned means effecting disablement at a different point from said first mentioned disabling means. 70

58. In a machine of the class described a plurality of settable keys, means for holding said keys when set, a key for releasing said keys from said holding means, a main operating mechanism, means for preventing operation of said releasing key during the forward movement of the operating mechanism, and means for disabling said preventing means near the end of the forward movement of said operating mechanism. 75

59. In a machine of the class described a plurality of columns of depressible keys, means for detaining said keys when depressed, individual column release keys for releasing a key depressed in any column independently of other columns, main operating mechanism, and means for preventing operation of said release keys upon operation of said main operating mechanism. 80

60. In a machine of the class described a plurality of depressible keys, means for holding a key when depressed, means controlled by said holding means for locking the undepressed keys against depression, and means for rendering said locking means ineffective. 85

61. In a machine of the class described a plurality of settable manipulative devices, means active upon setting of one of said devices for holding said device in set position and locking the other of said devices against setting movement, and means for preventing the locking of the unset devices upon setting one of said devices. 100

62. In a machine of the class described a plurality of settable keys, means effective upon setting of a key for preventing the setting of any other of said keys, and means for controlling said preventing means so as to permit setting of another key and restoration of the first set key. 110

63. In a machine of the class described a main operating mechanism, a release key therefor, a plurality of settable number keys, means for latching said keys when set, said means permitting release of a latched key upon setting of another key, and means preventing the release of a latched key and setting of another upon operation of said release key. 115

64. In a machine of the class described a main operating mechanism, a key for releasing said mechanism, a plurality of settable number keys, means for detaining said keys when set, connections from said operating mechanism for normally releasing detained 120

keys, and means controlled by said releasing key for disabling said connections.

65. In a machine of the class described a main operating mechanism, a plurality of releasing keys therefor, a plurality of settable number keys, means for detaining said keys when set, and connections operable by said operating mechanism when released by one of said releasing keys for releasing detained keys, said connections being rendered ineffective when said mechanism is released by another of said releasing keys.

66. In a machine of the class described a plurality of depressible keys, locking members adapted to retain the keys in depressed position when depressed, an operating mechanism, means for moving said locking members to lock said keys against depression as an incident to an operation of the operating mechanism, and means operated by said mechanism for releasing said keys for operation.

67. In a machine of the class described a plurality of depressible keys, an operating mechanism, means for holding said keys when depressed, said means serving to release a depressed key and detain another key upon depression of said other key, means operating upon said key holding means for locking all of the keys as an incident to the operation of said mechanism, and means for releasing said keys for manipulation during an operation of said mechanism.

68. In a machine of the class described, an operating mechanism, a release key therefor, a plurality of settable manipulative devices, means for locking said devices in either set or unset condition upon operation of said release key, and means for unlocking said devices during an operation of said mechanism.

69. In a machine of the class described, an operating mechanism, a plurality of settable manipulative devices, means for holding said devices when set, means operating upon said holding means for locking all of said devices as an incident to the operation of said mechanism, and means operated by said mechanism for releasing said devices to permit the subsequent setting of a device prior to the completion of the operation of the mechanism.

70. In combination, a set of bevel-edged disks, each mounted for movement in opposite directions and in a direction laterally of said opposite directions, a second set of bevel-edged disks mounted for sliding movement in the lateral direction of the first said set, and means for interposing any disk of the first set between two adjacent disks of said second set and thereby moving the disks of said second set into such contiguity as to prevent the interposition of any other disk of the first set between those of the said second set.

71. The combination in a keyboard section, of a pair of spaced plates connected together and having a plurality of keyways, a plurality

of keys one of which is mounted in each said key-way, a stop bar associated with said keys, and yielding means carried by one of said spaced plates for supporting said stop-bar and allowing it to move longitudinally and transversely.

72. In a machine of the class described, a plurality of key-stops, a stop bar provided with projections adapted to co-operate with said key stops, said bar being longitudinally movable and means for supporting said bar, said means permitting transverse movement of said bar.

73. In a machine of the class described a plurality of key stops, a stop bar provided with spaced projections, means for moving said bar longitudinally until one of said projections abuts a key stop, and means for permitting return movement of said bar after any key stop has been set subsequent to the initial longitudinal movement of said bar.

74. In a machine of the class described a plurality of typewriter keys, a plurality of settable controlling keys, an operating mechanism associated with said settable keys, means controlled by said operating mechanism for locking said typewriter keys, and means whereby said settable keys control the locking means.

75. In a machine of the class described a plurality of typewriter keys, a plurality of settable controlling keys, an operating mechanism associated with said settable keys, means controlled by said operating mechanism for locking said typewriter keys, and means controlled by said settable keys for determining the effectiveness of said locking means.

76. In a machine of the class described a plurality of typewriter keys, a main operating means, and means controlled by said operating means for locking said typewriter keys, said means controlled by said operating means serving to lock said typewriter keys both during and after an operation of the operating means.

77. In a machine of the class described a plurality of typewriter keys, a main operating means, and means controlled by said operating means for locking said typewriter keys, said means controlled by said operating means serving to lock said typewriter keys after an operation of the operating means.

78. In a machine of the class described a plurality of typewriter keys, a plurality of settable controlling keys, an operating mechanism associated with said settable keys, means controlled by said operating mechanism for locking said typewriter keys both during and after an operation of said operating mechanism, and means controlled by said settable keys for determining the effectiveness of said locking means to lock said typewriter keys after an operation of said mechanism.

79. In a machine of the class described a

- plurality of typewriter keys, a plurality of settable manipulative devices, an operating mechanism adapted to be controlled by said devices, a locking bar operated upon operations of said operating mechanism to control the locking of said typewriter keys, and means controlled by said settable devices for determining the effectiveness of said locking bar.
80. In a machine of the class described a plurality of typewriter keys, a plurality of settable manipulative devices, an operating mechanism adapted to be controlled by said devices, a locking bar operated upon operations of said operating mechanism to control the locking of said typewriter keys during and after an operation of said operating mechanism, and means controlled by said settable devices for determining the effectiveness of said locking bar.
81. In a machine of the class described a plurality of typewriter keys, a plurality of settable manipulative devices, an operating mechanism adapted to be controlled by said devices, a locking bar operated upon operations of said operating mechanism to control the locking of said typewriter keys during and after an operation of said operating mechanism, and means controlled by said settable devices for determining the effectiveness of said locking bar after an operation of said operating mechanism.
82. In a machine of the class described a plurality of typewriter keys, a plurality of settable manipulative devices, a main operating mechanism controlled by said devices, means for locking said typewriter keys after an operation of said mechanism in which one of said devices has been set, and means operable to disable said locking means upon an operation of said mechanism in which none of said devices is set.
83. In a machine of the class described, a plurality of value keys, a plurality of special shift keys, means whereby a certain group of the shift keys are locked upon depression of a value key, and means for preventing the depression of more than one key in any group which includes keys of the first mentioned group.
84. In a calculating machine, the combination of a plurality of number keys, a plurality of shifting keys, an operating mechanism, means for locking all of said keys during the forward movement of said operating mechanism, means for restoring said number keys at the end of the forward movement of the operating mechanism, and means for restoring said shifting keys near the end of the return movement of the operating mechanism.
85. In a calculating machine, the combination of a plurality of number keys, a plurality of shifting keys, an operating mechanism, means for locking all of said keys during the forward movement of the operating mechanism, means for restoring said shifting keys during the latter part of the movement of the operating mechanism, and means for restoring said number keys before the shifting keys have been restored.
86. In a calculating machine, the combination of a plurality of numeral keys, a numeral key locking bar, a plurality of shifting keys, a shifting key locking bar, an operating mechanism, means whereby said locking bars are moved to positively lock all of said keys during the forward movement of the operating mechanism, means whereby the shifting keys are released from their locking bar near the end of the movement of the operating mechanism, and means whereby the numeral keys are released from their locking bar before the shifting keys are released.
87. In a calculating machine, the combination of a plurality of numeral keys, a numeral key locking bar, a plurality of shifting keys, a shifting key locking bar, an operating mechanism, means whereby said locking bars are moved to positively lock all of said keys during the forward movement of the operating mechanism, means whereby said numeral keys are released from their locking bar at the end of the forward movement of the operating mechanism, and means whereby said shifting keys are released from their locking bar near the end of the return movement of the operating mechanism.
88. In a calculating machine, the combination of a plurality of rows of setting keys, a normally ineffective resistance device, and means for rendering said device effective upon the depression of any key in a row to increase the resistance to the subsequent depression of any other key in the same row.
89. In a calculating machine, the combination of a keyboard having a plurality of rows of setting keys, means operating to retain any depressed key in set position and to permit its restoration upon the depression of another key in the same row, and optionally operable devices for causing said retaining means to lock the undepressed keys of any row in normal position upon the depression of any key in said row.
90. In a calculating machine, the combination of a main operating frame, a keyboard having a plurality of rows of keys, each row comprising settable numeral keys and a correction key, a key locking device common to all the keys, and means for rendering said key locking device effective to lock the correction keys during the initial portion of the forward movement of said operating frame.
91. In a calculating machine, the combination of a plurality of numeral keys and a plurality of shifting keys arranged in a row adjacent to one row of said numeral keys, means for locking any one of said keys in its depressed or operative position, operating mechanism, means for releasing said numeral keys, means for releasing said shifting keys,

connections from said numeral key releasing means to said operating mechanism, connections from said shifting key releasing means to said operating mechanism, and optionally operable means for preventing the operation of said shifting key releasing means by said operating mechanism.

92. In a machine of the character described, the combination of depressible amount keys extending in a row from front to rear, detent devices for the keys including an elongated member for said row of keys extending throughout the row for cooperating with any one of the keys to be moved longitudinally thereby and extending forwardly beyond the key-row; an upstanding special key in line with the amount keys, and camming means between said special key and the forwardly extending portion of the elongated member.
